UNITED STATES PATENT OFFICE.

CHARLES BURNHAM, OF LOS ANGELES, CALIFORNIA, ASSIGNOR TO BURNHAM BASKET COMPANY, A CORPORATION OF CALIFORNIA.

BOX-MAKING MACHINE.

1,119,340.

Specification of Letters Patent.

Patented Dec. 1, 1914.

Application filed August 22, 1911. Serial No. 645,323.

To all whom it may concern:

Be it known that I, CHARLES BURNHAM, a citizen of the United States, and a resident of Los Angeles, county of Los Angeles, and State of California, have invented certain new and useful Improvements in Box-Making Machines, of which the following is a full, clear, and exact description.

This invention relates more particularly to basket or box machinery such as disclosed in my pending application Sr. No. 469,250, filed December 26, 1908, in which boxes or like containers for berries or other fruit are made from veneer.

The primary object of the invention is to provide a simple and efficient automatic machine in which box shooks may be automatically fed to die mechanism and there formed into the desired shape, and wherein a strip 20 of metal is automatically bent the desired shape and applied as a single piece to the bent box form and after the boxes are completed they are automatically stacked and discharged from the machine.

Other objects of the invention are to provide simple and efficient means for feeding the metal binding stock as a narrow strip to the machine; to provide simple means 30 for bending the strip substantially V-shaped to fit over the open end of the box; to provide means for tilting and for cutting off the formed metal binding the desired length and feeding such strip as a single piece in position to be bent to the shape of the box, 35 which for packing berries is usually of a rectangular form in plan; to provide simple and efficient means for bending the formed tin or metal strip around a substantially rectangular body or element and to 40 hold the same to receive the edges of the box form, and to provide means whereby the free end of the binding strip may be made to overlap.

Another object of the invention is to provide simple and efficient feed mechanism for the veneer shooks of which the box body is made, and to provide means whereby a large number of shooks may be readily placed in position to be fed to the box-forming means.

A further object of the invention is to provide simple and efficient die mechanism for forming the box into the desired shape; to provide a carrier for the shooks to place the same in position to be operated on by 55 the die mechanism, and to provide simple

means whereby after the shooks have been made into box form, the metal binding may be automatically applied to the box and crimped thereon and the completed box placed back into the carrier.

A still further object of the invention is to provide simple and efficient pneumatic means whereby the shooks may be automatically removed from a plurality of magazines and the shooks arranged cross-wise and automatically discharged into a carrier to be fed to the die mechanism.

A still further object of the invention is to provide simple and efficient means for discharging the completed boxes from the 70 machine and to stack the same as they are discharged.

With these and other objects in view, the invention will be hereinafter more particularly described with reference to the accompanying drawings, which form a part of this specification, and will then be pointed out in the claims at the end of the description.

In the drawings, Figure 1 is a side elevation of one form of machine embodying my invention, looking in the direction of arrow I, Figs. 2, 4 and 5. Fig. 2 is a plan view, looking in the direction of arrow II of Figs. 1, 3 and 5. Fig. 3 is an elevation of the 80 machine looking from the side opposite to that shown in Fig. 1, looking in the direction of arrow III of Figs. 2, 4 and 5. Fig. 4 is an end elevation of that part of the machine from which the metal binding stock is fed, 85 looking in the direction of arrow IV of Figs. 1, 2 and 3. Fig. 5 is an end elevation, showing the shook magazines and looking at the machine from the opposite end to that shown in Fig. 4 in the direction indicated by arrow V of Figs. 1, 2 and 3. Fig. 6 is a sectional plan view, partly in elevation, taken on the line VI—VI of Fig. 1. Fig. 7 is a top plan view of one of the shook 90 magazines detached from the machine. Fig. 8 is an elevation of the magazine frame. Fig. 9 is a front elevation of the frame shown in Fig. 8. Fig. 10 is a sectional plan view taken on the line X—X of Fig. 9. Fig. 11 is a sectional plan view taken on the line, 95 XI—XI of Fig. 12 of the magazine frame. Fig. 12 is a fragmentary view, partly in section and partly in elevation, of the upper part of the magazine frame. Fig. 12^a is a fragmentary sectional view, partly in eleva-

tion, of the upper part of the magazine frame, showing the auxiliary feed for the shooks when the magazine holding member is being placed in position. Fig. 13 is a sectional plan through one of the magazines, taken on the line XIII—XIII of Fig. 8. Fig. 13^a is a sectional view taken on the line XIII^a—XIII^a of Fig. 13. Fig. 14 is a plan view of a part of the follower feed of the magazine. Fig. 15 is an elevation looking in the direction of line XV—XV of Fig. 14. Fig. 16 is a view of one member of the auxiliary feed located at the upper part of the magazine. Fig. 17 is a side elevation of Fig. 16. Fig. 18 is a detail perspective of the fingers or devices for engaging the edges of the shooks in the magazine. Fig. 19 is a sectional plan, partly in elevation taken on the line XIX—XIX of Fig. 20, showing the means for rotating the follower feed screw. Fig. 20 is a detail of the feed screw for the shooks, showing in section part of the means for intermittently rotating said screw. Fig. 21 is a plan view, partly in elevation, showing one form of means for lifting the followers within the magazines after the shooks are in position to be fed. Fig. 22 is a side elevation, partly broken away, of the operating lever shown in Fig. 21. Fig. 23 is a transverse section taken on the line XXIII—XXIII of Fig. 21 showing how the operating lever rocks the shaft in either direction so that either follower of either of the magazines may be forced upward. Fig. 24 is a detail perspective view of one of the magazine holders. Fig. 25 is a plan view, partly in section, of a part of the mechanism for operating the magazine feed screws taken on the line XXV—XXV of Fig. 26. Fig. 26 is a fragmentary elevation, partly in section, of the mechanism shown in Fig. 25 for operating the feed screws and thereby feeding the shooks within the magazine. Fig. 27 is a fragmentary plan, partly in section, of a part of the pneumatic means for transferring the shooks. Fig. 28 is an end elevation of Fig. 27. Fig. 29 is a view partly in section and partly in elevation, the section being taken on the line XXIX—XXIX of Fig. 27. Fig. 30 is a section taken on the line XXX—XXX of Fig. 27. Fig. 30^a is a section taken on the line XXX^a—XXX^a of Fig. 27. Fig. 31 is a plan view, partly in section, showing a part of the means for elevating and lowering and also rotating the pneumatic shook transfer device, the section being taken on the line XXXI—XXXI of Fig. 32. Fig. 32 is a vertical section, partly in elevation, taken on the line XXXII—XXXII of Fig. 31. Fig. 33 is a fragmentary view of a part of the shook carrier which receives the shooks from the pneumatic transfer means and carries it in position to be operated on by the box-forming mechanism, and also to re-

ceive and carry the completed boxes in position to be discharged from the machine. Fig. 34 is a fragmentary transverse vertical section taken on the line XXXIV—XXXIV of Fig. 33. Fig. 35 is a section taken on the line XXXV—XXXV of Fig. 33. Fig. 36 is a detail enlarged view of one of the connections adapted to engage a cam and to be operated thereby to shift the position of the shook holding means arranged within the shook carrier. Fig. 37 is a detail perspective view of one of the corner pieces adapted to receive and hold the completed box or basket after being formed to carry the same into position to be discharged from the machine. Fig. 38 is a detail view, partly in section and partly in elevation, of the means for controlling the valves which feed the shooks in order that the air may act properly to lift the shooks from the magazine and to discharge the same into the carrier, the section being taken on the line XXXVIII—XXXVIII of Fig. 39. Fig. 39 is a fragmentary view, partly in section and partly in elevation, of the mechanism shown in Fig. 38. Fig. 40 is a detail view, partly in section, of the means for intermittently rotating the carrier shaft, the view being taken on the line XL—XL of Fig. 41. Fig. 41 is a fragmentary view, partly in section and partly in elevation, of the mechanism shown in Fig. 40. Fig. 42 is a fragmentary plan view, partly in section, of the means for feeding the metal binding strip to the machine. Fig. 43 is an elevation, partly in section, the section being taken on the line XLIII—XLIII of Fig. 42 of the feed mechanism. Fig. 44 is a fragmentary plan view of the means for forming the metal strip into substantially V-shaped form in order that it may fit on the inner and outer sides of the box edge when applied to the box form. Fig. 45 is a transverse section, partly in elevation, taken on the line XLV—XLV of Fig. 44 of the forming mechanism. Fig. 46 is a transverse section taken on the line XLVI—XLVI of Fig. 44, the parts being shown in a different position from that shown in Fig. 45. Fig. 47 is a fragmentary inverted plan, partly in section taken on the line XLVII—XLVII of Fig. 45. Fig. 48 is a detail perspective view of one of the forming guide supports. Fig. 49 is a fragmentary view, partly in section and partly in elevation, of means for feeding the formed strip, the section being taken on the line XLIX—XLIX of Fig. 50. Fig. 50 is a sectional view, partly in elevation, taken on the line L—L of Fig. 49. Fig. 51 is an enlarged fragmentary view of the feed rolls. Fig. 52 is a sectional view, partly in elevation, of the tilting rolls for tilting the metal into the position which it should assume before being bent around the anvil or ele-

ment preparatory to its application to the box form. Fig. 53 is an elevation of the guide for the formed binding strip looking in the direction of arrow LIII of Fig. 50. Fig. 54 is a section taken on the line LIV—LIV of Fig. 50. Fig. 55 is a section taken through the guides but beyond the section shown in Fig. 54. Fig. 56 is a fragmentary plan view showing part of the reciprocatory frame and means for holding the metal binding strip preparatory to moving the same adjacent to the die mechanism, and also showing the means for cutting off the formed strip the proper length. Fig. 57 is a fragmentary elevation of the cutting means. Fig. 58 is a vertical section, partly in elevation, of the mechanism shown in Figs. 56 and 57. Fig. 59 is a transverse section taken on the line LIX—LIX of Fig. 56. Fig. 60 is a fragmentary sectional view of a part of the gripping and cutting mechanism, the section being taken on the line LX—LX of Fig. 58. Fig. 61 is a fragmentary sectional view taken on the line LXI—LXI of Fig. 57. Fig. 62 is a fragmentary plan view, partly broken away and partly in elevation, showing a part of the binding strip as it is fed inward and which by movement forms the initial bend about the anvil, the parts being shown in a reversed position to that shown in Fig. 6. Fig. 63 is a vertical section, partly in elevation taken on the line LXIII—LXIII of Fig. 62. Fig. 64 is a vertical section taken on the line LXIV—LXIV of Fig. 62, showing one of the bending jaws for giving the first bend to the binding strip. Fig. 65 is a fragmentary view, partly in section, taken on the line LXV—LXV of Fig. 62, showing a device for holding the binding strip in the bending jaws, and also showing in dotted lines how this holding device is released. Fig. 66 is a view showing in plan one of the second bending jaws, that is the jaw that gives the second bend about the anvil or forming element. Fig. 67 is an elevation showing one of the jaws swung downward. Fig. 68 is an end elevation of one of the second bending jaws. Fig. 69 is a fragmentary plan, partly in section, showing the two second bending jaws in position to give the final bending to the binding metal strip, the jaws being shown on the side of the anvil opposite to that of Fig. 62. Fig. 70 is a sectional view taken on the line LXX—LXX of Fig. 69. Fig. 71 is a fragmentary section taken on the line LXXI—LXXI of Fig. 69. Fig. 72 is a longitudinal section, partly in elevation, showing the second bending jaws as they move inward toward each other to give the second or final bend to the binding strip and to cause the ends of said binding strip to overlap. Fig. 72^a is a sectional plan showing the anvil or former for the binding strip and the jaws for bending the strip about the anvil. Fig. 73 is an enlarged vertical section, partly in elevation, of the die, plunger and crimping mechanism, taken on the line LXXIII—LXXIII of Fig. 74. Fig. 74 is a sectional plan view taken on the line LXXIV—LXXIV of Fig. 73. Fig. 75 is a sectional plan view taken on the line LXXV—LXXV of Fig. 73. Fig. 76 is a detail plan view of the anvil or former which is carried by the plunger element. Fig. 77 is a section, partly in elevation, taken on the line LXXVII—LXXVII of Fig. 76. Fig. 78 is a section taken on the line LXXVIII—LXXVIII of Fig. 76. Fig. 79 is a fragmentary view of one of the crimping or pinching devices. Fig. 80 is an inverted plan view of the device shown in Fig. 79. Fig. 81 is a sectional view, partly in elevation, of the crimping device, the section being taken on the line LXXXI—LXXXI of Fig. 79. Fig. 82 is a fragmentary plan, partly in section, of a part of the box-forming plunger. Fig. 83 is a sectional view, taken on the line LXXXIII—LXXXIII of Fig. 84. Fig. 84 is an elevation, partly in section, of the box-forming plunger. Fig. 85 is a detail section of one of the plunger elements, the section being taken on the line LXXXV—LXXXV of Fig. 86. Fig. 86 is an inverted plan view, of the element shown in Fig. 85. Fig. 87 is a detail side elevation of one of the corner pieces of the anvil about which the binding metal is bent. Fig. 87^a is an inverted plan view of the corner piece, shown in Fig. 87. Fig. 88 is a detail perspective view of one of the pivotally held members of the box-forming plunger. Fig. 89 is a plan view of a part of the machine, showing the die mechanism in plan. Fig. 90 is a fragmentary vertical section taken on the line XC—XC of Fig. 89. Fig. 91 is an enlarged side elevation of one of the die folding sides or plates. Fig. 92 is a detail end view of one of the folding members with the box-stripping hook or device held thereto. Fig. 93 is a detail plan of one of the yielding base plate members of the die mechanism. Fig. 94 is an end view of the member, shown in Fig. 93. Fig. 95 is a section, partly in elevation, showing part of the die mechanism and means for operating the same. Fig. 96 is a detail perspective view of one of the levers for operating the box-folding sides or plates. Fig. 97 is a plan view of one of the die blocks or members to which the lever shown in Fig. 96 is held. Fig. 98 is a detail side elevation, partly in section, of one of the blocks shown in Fig. 97, the part in section being on the line XCIII of Fig. 97. Fig. 99 is a fragmentary sectional view showing the plunger and crimping means, part of the carrier, and the vertically movable die or box former before the box shooks

130

have been removed by the die from the carrier. Fig. 100 is a view somewhat similar to Fig. 99 except that the parts are in a different position, this view also showing the 5 binding strip in position to be forced over the upper edge of the box. Fig. 101 is a view similar to Fig. 100 except that the parts are in different position, and showing the box prior to having the binding 10 strip applied thereto. Fig. 102 shows the box after the metallic binding strip has been applied and crimped. Fig. 103 is a fragmentary plan view of a part of the turret showing the same in position under the dis- 15 charging chute ready to have the completed box forced therefrom. Fig. 104 is a vertical section taken on the line CIV—CIV showing the automatic discharging mechanism. Fig. 105 is a view looking at the discharging 20 mechanism and in the mouth of the discharging chute. Fig. 106 is a detail of one of the turret members. Figs. 107 and 108 are fragmentary detail perspective views of a part of the binding strip. Fig. 109 is 25 a plan view showing the binding strip completed and bent ready to be applied to the box. Fig. 110 shows how the binding strip is first forced downward and then upward to permit one end to overlap the other end 30 of the strip preparatory to being applied to the box form. Fig. 111 shows the binding strip completed and ready to be applied to the box. Fig. 112 shows a detail of one of the 35 shooks. Fig. 113 is a plan view of the shooks in a crossed position ready to be folded, and Figs. 114, 115 and 116 are vertical sections of the box, showing the same from the time it is folded until the binding 40 strip has been applied and crimped thereto. While I show the features of the invention as applied to a particular form of machine, it will be understood that many of the 45 features may be used in connection with other forms of machines and that some of the parts may be dispensed with or other features substituted therefor without departing from the spirit of the invention.

In the general operation of the machine, a 50 metallic strip is fed from a reel or otherwise suitably supported convenient to the machine, and this strip by suitable mechanism is fed to what I term forming mechanism, that is the metal is bent or formed lengthwise thereof so as to be substantially 55 V-shaped in order to fit over the edge of the box form. This strip is fed inward and tilted and after being tilted so that it will assume a proper position relative to the edges of the box and the anvil or former 60 about which it is bent according to the shape of the box, the strip is then cut off the proper length. The strip is then fed forward on one side of a substantially rectangular anvil having a shape corresponding to the shape 65 of the open end of the box and until the said

strip meets the anvil, when the jaws into which the strip has been previously fed by engagement with the former or anvil will bend both ends of the strip on opposite sides thereof making the same substantially U-shaped. A second pair of jaws engages the free ends of the binding strip and forces the same on the remaining side of the anvil and causes one end of the strip to overlap the other. The shooks of which the box body 70 is made are placed in two magazines located adjacent to one end of the machine, and these shooks are automatically fed upward in position to be removed therefrom. A reciprocatory and rotary pneumatic device 75 is provided for this purpose and this device is automatically controlled so that the shooks will be picked up first from one and then from the other magazine so that the shooks as thus picked up will lie crosswise 80 and at substantially right angles to each other. The pneumatic device discharges the crossed shooks into a rotary carrier or turret. A movement is given to the carrier 85 and this places the crossed shooks in the path of box-forming mechanism, and at the proper time this mechanism operates to form the shooks into box form and carries the box from above the carrier and forces 90 the upper edge thereof into the binding strip. The binding strip is then pinched on to the shooks thus holding the box shooks permanently together in box form. Mechanism is provided for stripping the box 95 and causing the completed box to be deposited into the carrier, and the carrier as it feeds new shooks crosswise to the die 100 mechanism conveys the completed box into position to be discharged. The completed box is forced out of the carrier into a chute 105 and properly stacked and may be removed in any desired way.

The binding metal is usually of tin and is in the form of a narrow strip, as 10, Figs. 1 and 43, and the metal strip may be supported as a roll or reel or otherwise convenient to the machine and passes to a suitable feed mechanism 11. This feed mechanism, Figs. 1, 2, 6, 42 and 43, is shown as having two feed rolls 12 and 13. The feed roll 12 is held to a shaft 14 and the feed roll 13 to a shaft 15 both of which extend transversely of the machine frame 15^a at the upper portion thereof and at one end of the machine. On the shaft 14 is a gear 16 which is in mesh with a gear 17 held to the shaft 15 by which the two feed rolls 12 and 13 may be rotated in unison. The shaft 14 is mounted upon an arm 18 which is pivoted at 19 to the machine frame 15^a, and held to the upper end of this arm is one end of a spring 20, one end of which, as 21, is secured to the machine frame 15^a and the other end has a thumb nut 22 held thereto by which the tension of the spring 20 may be varied, 130

the said spring serving to hold the feed roll 12 in yielding engagement with the feed roll 13 to compensate for the various thicknesses of the tin binding strip which at best 5 would not likely be very great.

A bevel friction wheel 23 is secured to the shaft or stud 15, and adapted to engage the beveled surface thereof is a second bevel friction wheel or gear 24. The friction surface 10 of these wheels may be of any suitable material. The wheel 24 is clamped and rigidly held to a thimble or bushing 25 between the washer 26 and flange 27 of the bushing 25 by means of a nut 28. The thimble 25 is held to rotate with the shaft 29 and is keyed thereto so as to be adjustable lengthwise of said shaft, and said thimble 25 is rotatable in a sleeve 30. This sleeve is normally held against rotation in a split 15 boss of a bracket or frame member 31. The sleeve 30 has a knurled part 32 and a threaded portion 33 to engage a threaded opening in the frame member 31, and said sleeve is held between the flange 27 and a collar 34 secured to the end of the thimble 25. By 20 manually rotating the knurled part 32 and sleeve 30 the friction gear 24 may be moved toward or from the shaft or stud 15 and thus vary the speed of the feed rolls 12 and 25 13 and consequently the feed of the binding metal.

The shaft 29 is journaled in the frame bracket 31 and this bracket is pivoted at its lower end to a part of the machine frame 35 15^a and is held to rock with the shaft 35. At the upper end of the frame above the shaft 29 is a lug 36 and passing through this lug is a rod 37. This rod is screw threaded at one end and is provided with 40 a thumb nut 38 adapted to engage the lug 36 and on the other end of said rod is a collar 39. This collar 39 may be held by a screw thread or otherwise to the rod 37 and interposed between said collar 39 and a free 45 collar or washer 40 is a spring 41 intended normally to force the shaft 29 and the friction gear or wheel 24 yieldingly against the friction wheel or gear 23 to rotate the feed rolls, the tension of said spring being varied 50 through the thumb nut 38. A sprocket wheel 42 is secured to one end of the shaft 29 and passing around this sprocket wheel is a sprocket chain 43. This chain 43 passes around a sprocket wheel 44, Figs. 1, 4 and 55 6, and said sprocket wheel 44 is secured to the main driving shaft 45 located at the lower part of the machine and at one side thereof. An arm 46 is pivotally held at 47 to one end of the frame and on the outer 60 end of this arm is an idler roll 48 which is adapted to engage the sprocket chain 43 and serves to take up the slack and to permit proper tension to be given to the chain during the swinging movement of the shaft 29. 65 By this means the binding metal may as a

strip be fed forward positively and properly and at the desired speed.

To bend the metal binding strip lengthwise and form it substantially V-shaped in order that it may fit properly over the 70 upper edges and around the box when the latter is formed, I provide what I term forming mechanism 49 arranged at the upper portion of the machine immediately adjacent to the feed mechanism 11. This forming mechanism, Figs. 1, 2 and 44 to 48 may be variously constructed. As shown a bar or member 50 is secured by bolts 51, or otherwise, to the upper part of the machine frame, and said forming bar or member 80 may have a limited adjustment by the bolts 52. At intervals along the bar 50 the machine frame 15^a is cut away, as at 53, and in such cut-away portion and held to the bar are brackets 54. These brackets 54 are secured to the bar 50 by screws 55, or otherwise, and said bracket is formed by two upright parts or portions 56 which are connected by an integral part 57. Two levers 58 and 59 are each pivoted, as at 60, between the bracket of parts 56 and on the lower end of said levers 58 and 59 are guides 61. These guides 61 are bar-like in form and are each cut away at their inner edge and one of said bars is movable with the 90 levers 58 and the other with the levers 59 when said levers are moved on their pivots as will be presently described. An adjustable cap member or part 62, Figs. 45 to 48, has pins 63 extending into openings in the 100 guides 61. The adjustable members 62 each have a slot 64 through which pass a vertically arranged bolt 65 to permit adjustment of said adjustable members and the guides carried thereby, and said members 62 each 105 have an upwardly extending angular portion 65^a and is adapted to be guided on the lower part of the levers 58 and 59. A bolt 66 passes through a slot 66^a in each plate and said bolt has a threaded end engaging a 110 threaded opening in one of the levers to adjust each cap plate 62 and coöperating guide 61.

The upper ends of the levers 58 and 59 are connected by links 67 to a centrally arranged stud 67^a forming a toggle lever connection and on the stud 67^a are boxes 68 which are adapted to move vertically in slots 70 in the upper end of the parts 56 of the brackets 54 and serve to guide the stud 115 67^a vertically in the brackets and to force the lower end of the levers inward to carry the guides 61 toward the forming bar 50 or outward according to the direction of movement of the stud 67^a.

A rock shaft 71 is held at the upper part of the machine and held to said shaft are arms 72 the outer ends of which are provided with slots 73 to receive boxes 68 carried by the shaft or stud 67^a so that when 130

the shaft 71 is rocked a downward or upward movement will be given to the shaft 67^a and through it move the levers 58 and 59 on their pivots. From each of the arms 5 72 projects a lug or part 73^a and interposed between said part 73^a is a spring 74^a fitting around the reduced end of an adjustable screw 75 which is located in a recess in a part of the machine frame so that 10 by adjusting said screw the tension of the spring 74^a may be varied. These springs tend normally to force the outer ends of the arms 72 and the stud 67^a downward, and through the levers 58 and 59 force the 15 guides 61 inward. To raise the arms 72 and force the same against the action of the springs 74^a of the arms 72, I provide a plurality of arms 76, one for each spring 74^a, and each of said arms 76 is fixed to the 20 shaft 71 and has an angular portion 77 in which is a screw 78, which when the shaft 71 is rocked will engage the projecting part 73^a of each pair of arms 72 and cause the part 73^a to be forced downward against the 25 action of the spring 74^a. The shaft 71 has an operating arm 79 fixed thereto, and pivotally held to the outer end of said arm is a connecting rod 80, the lower end of which carries a trundle adapted to be operated by 30 a cam 81, Fig. 1, which is held to rotate with the main driving shaft 45. The rod 80 may be provided with a turn-buckle to lengthen or shorten the same, as shown at 35 82 in dotted lines in Fig. 1, and said rod when the shaft 45 is rotated will oscillate or rock the shaft 71 and through the mechanism already described force the guides outward or permit the guides to be moved inward through the springs 74^a to properly 40 align and guide the binding strip preparatory to the same being formed or bent V-shaped lengthwise of said strip. The purpose of this centralizing mechanism is to center and straighten edgewise binding wire 45 or strip of varying width and which may be curved or twisted throughout its length. These inaccuracies are liable to occur in a binding made by rolling or flattening a round wire, though where a ribbon of substantially uniform width is used, as where 50 the binding is made by slitting a wide ribbon, the guides and some other features may be dispensed with and a more simple mechanism employed.

55 Under the guides 61 and extending lengthwise under the bar 50 in a vertical line therewith is a forming bar 83. This bar 83 has a tapered upper edge substantially V-shaped in form and corresponds 60 to the shape of a recess 84 in the lower edge of the bar 50. The bar 83 is secured to a cross-head 85 by means of the screws 86 or otherwise, and said cross-head 85 is adapted to be moved vertically in the guides 87 of 65 the machine frame. The cross-head is pro-

vided with lugs 88, Fig. 1, in which is a shaft 89, and connected to the shaft are rods 90 located adjacent to the ends of the cross-head, and these rods are connected to rock arms which have trundles on their outer ends that are engaged by cams 91 secured to the drive shaft 45, and said rods may be adjustable by means of turn-buckles 92 to properly adjust the cross-head and the forming bar 83 carried thereby. As the drive shaft is rotated the cross-head will be reciprocated and such reciprocation will force the upper edge of the bar 83 into the recess 84 of the bar 50 to bend or form the binding strip lengthwise in substantially V-shaped form.

The binding strip is rigidly held by the feed mechanism 11, and interposed between the forming mechanism just described and said feed mechanism 11 are a pair of rolls 93 and 94. These rolls, Figs. 1 and 43, are held to studs projecting outward from the machine frame and said rolls serve not only to guide the strip properly to the forming mechanism but also serve to cause a loop 90 to be formed in the binding strip, as at 95, Fig. 43, in order to provide sufficient material to be fed forward for the lengthwise bending of the strip without stopping the feed from the reel or roll and also to permit the strip to be held stationary during the lengthwise bending without affecting the rotary movement of the feed mechanism rolls 12 and 13.

A second feed mechanism is arranged adjacent to the lengthwise forming mechanism and this feed mechanism is operated in such a way and is so constructed that it will advance the formed strip just sufficient to make a strip of a length corresponding 100 to the size of the box to be formed. This mechanism 96, Figs. 1, 49 to 51, has two rolls 97 and 98, the former being held to shaft 99 and the latter to a shaft 100. The roll 97 is provided with a groove 101 formed 110 in an annular ring which is held by screws 103 between a disk 102 and the body portion of the roll, or the said roll may be otherwise constructed, while the roll 98 has a disk-like member forming an annular projecting rib 104 adapted to fit into the groove 101. The groove 101 and rib 104 are shaped according to the formation of the binding strip and are adapted to positively hold the same between the surfaces of said rolls. The 120 roll 97 is held to a gear 105, and the roll 98 is held or formed as a part of a gear 106 which gears intermesh and serve to rotate the two rolls in unison. The shaft 99 is supported by arms 107 pivotally held to a stud 125 108 on the machine frame, and the roll 97 may be held in engagement with the roll 98 by a spring 108^a secured at one end to one of the arms and at its other end to the machine frame.

To positively drive the rolls and to time the same with relation to other parts of the machine any suitable means may be employed. As shown the roll 98 has a projecting annular rib 109 and adapted to engage said rib are friction dogs 109^a forming a part of a friction clutch 110. The dogs 109^a have slots or recesses to span the rib 109 and have their lower ends loosely held in notches in a collar 111 which is held to rotate on the stationary shaft 100. Pins 112, one for each dog, project radially from the collar 111 and held to each pin is a spring 113, one end of which connects with the dog tending to hold each dog in gripping contact with rib 109 in a position ready to move the wheel 98 through the rib 109 in one direction, but will allow a free return of the dogs. The collar 111 is integral with a gear 114 and serves as the hub therefor, and when the gear is moved the dogs will move the feed wheels through the dogs positively gripping the rib 109, while the dogs become disengaged when the gear 114 and collar 111 are moved in the opposite direction. The gear 114, Figs. 1 and 49, is in mesh with a rack 115, the said rack being held to move vertically in the guides 116. The guides may be attached to the frame or formed as a part thereof, and passing through the guides and connected to the rack is a rod 117. This rod 117 is connected to a rock lever 118 which carries a trundle 119. This trundle is operated by a cam 120 on the drive shaft 45 to reciprocate the rack 115, a spring 121 being provided to force the rack downward and to keep the trundle against the periphery of the cam 120. A projection 122 is carried by the rack 115 and in this projection is a screw 123, the lower end of which is adapted to engage a part 124 on the guides 116. The purpose of the projection 122 and the stop 124 is that the rack may be operated just the desired distance by the cam 120 in order to rotate the feed rolls properly to feed just the right length of strip. It will be seen that the screw 123 by its engagement with the stop 124 will limit the downward movement of the rod 117 according to the adjustment of the screw, while the cam always raises the rack to the same height, thus a very exact feed may be obtained.

The binding metal as it is fed forward through the forming mechanism and after it passes the feeding mechanism 96 is tilted in order that it might be positioned properly with respect to the upper edges of the box, and in order that the same may be properly held to receive the edge of the box when formed. The binding strip both before reaching the feed mechanism 96 and afterward is suitably guided as it is fed forward and said guiding means may be in the form of plates or bars 125 and 126.

These bars may be divided into two parts extending on opposite sides of the feed rolls 97 and 98 and the said bars form a recess or groove 127 between them. This groove on one side of the feed rolls is tapered and is of the form shown in Fig. 53. At the side opposite the feed rolls the said bars become tilted or arranged at an angle and the groove in this case may be circular for a part of its length as at 128, Fig. 54, and large enough to guide the material. At a point farther inward, as indicated by arrow LV, Fig. 1, the said bars are still in a tilted position and the groove changes to that shown in Fig. 55, as at 129, and this groove extends to a point adjacent the tilting rolls 130 and 131, the said tilting rolls being best shown in Fig. 52. These rolls are arranged at an angle with respect to a vertical plane, the roll 130 being grooved while the roll 131 has a tapering peripheral surface adapted to fit the groove so that the formed metal will be gripped by said rolls and properly positioned thereby. The roll 131 is held to rotate on a stud 132 carried by a part of the machine frame, and the roll 130 is held to rotate on a stud 133 carried by an arm 134 which is pivoted at one end to a part of the machine frame, as at 135, Fig. 1, and the free end is normally forced toward the roll 131 by a spring 136.

The tilting of the formed metal binding is important, otherwise it cannot be successfully bent about the corners of the anvil or former to receive the box body as will be hereinafter explained. The binding must be so positioned that it will not capsize while being bent box-form, in which case it will not make a rim that will open downward to properly receive the top edge of the box body but will either cause one side of the binding to open outward or to move inward while being bent about the anvil.

After the binding strip has been formed and tilted and fed forward far enough to give the length of the strip required, it is necessary to cut the strip off at the proper point and hold the strip severed from the stock. One means for severing and holding the stock is shown in more or less detail in Figs. 56 to 61. As shown the strip is fed forward along a groove 137, Fig. 59, conforming substantially to the shape of the strip, and said groove is formed in one face of a bar 138 carried by a reciprocatory frame-bar 139, the strip of binding metal before reaching the bar 138 being made to pass between two jaws 140 and 141. The jaw 140 carries a substantially V-shaped tooth or engaging part 142 which is clamped between a part of the jaw and a cap plate 143 by a screw 144. This gripping part 142 of the jaw 140 is opposed to the gripping member 145 carried by the jaw 141. The gripping part 145 is in alignment with a

part 142, and of the same length and both gripping parts are arranged at an angle corresponding substantially to the tilted position of the binding strip, the part 145 being 5 slidingly held in a recess 146 in the jaw 141. A rod 147 connects with the part 145 and on the outer end of said rod are nuts to limit the downward movement of the part 145 relatively to the rest of the jaw 141, and 10 arranged around the rod is a spring 148 one end of which engages the under side of the recess portion of the jaw or of a separate cap plate 149 and the other end of said spring arranged in a recess in the upper portion 15 of the clamping or gripping part 145. A knife 150 is held in the jaw 141 adjacent to the gripping part 145. This knife is held against movement by a screw or bolt 151 and another screw 152 located at one edge of 20 the knife by which the knife may be properly positioned. The knife has an edge to properly cut the strip and serves as one member of the shearing means, and the clamping part 142 serves as the other member 25 of said shearing means, the said part 142 being adjusted through a screw 153. The jaws 140 and 141 are constructed to move toward each other and during this movement the binding strip is cut transversely, the purpose of the groove 154 of the 30 knife and the groove 155 in the clamping member 145 being to prevent the formed strip from having its shape changed during the cutting operation. The principal purpose 35 of the block or gripping part 145 being forced into engagement with the block gripping part 142 is to reform that end of the metal binding strip so that when the other end is lapped or forced into it the two ends 40 will fit nicely and neatly, otherwise one overlapped part will project considerably above the other when the rim is crimped on the finished basket. By having the two ends meet properly makes it possible for the hook 45 to hold the lapped ends of the binding strip, though in addition to these important features, the clamping of the strip between the parts 145 and 142 makes it possible to still cut the material well even when the knives 50 are quite dull. The jaw 141 may be formed as a part of a lever 156 which is angular in form, and the jaw 140 is carried by a lever 157 of a bell-crank type and both levers are pivoted to a stud 158. The levers at their 55 lower ends extend on opposite sides of the pivot and are connected by links 158^a to a vertically movable rod 159 forming a toggle joint connection, so that by reciprocating the rod 159 the jaws 140 and 141 will be brought 60 toward each other and in doing so the metal strip will be clamped between the parts 142 and 145 and then the knife 150 will cut the strip the proper length, the length of the strip being determined by the feed as previously described. The rod 159 extends

downward and is connected to an arm which carries a trundle at one end thereof, the said trundle being engaged by a cam 160 on the main drive shaft 45 to operate said rod as the said shaft is rotated.

The strip as it is fed along the bar 138, Fig. 59, and in the groove 137 is held from falling out of said groove by a shutter or bar 161. This shutter is carried by a beam or bar 162 and this beam is adapted to rock with a shaft 163. The shaft 163 is held to the shutter 162 and rocks in the bearing or brackets 164 which are fastened to the machine frame and are located at both ends of the shutter and therefore do not move with the reciprocating frame bar 139. The bracket 164 nearest the transverse cutting knife has a strip or guide held to the inner edge thereof provided with a groove to receive the binding strip, while the other bracket 164 is not provided with such a guide. The shutter 162 carries an integral arm 165, and this arm at its outer end is connected to a rod 166. The lower end of the rod 166 is pivotally held to a pivoted arm or lever which carries a trundle at one end and which is engaged by a cam 167, Fig. 1, arranged on the main drive shaft 45, so that as this latter shaft is rotated the cam will cause an oscillatory movement to be given to the shutter bar 161 to release the binding strip held in the bar 138.

A reciprocating frame 168 to which the bar 139 is held carries the severed binding strip to an anvil or former 169, Figs. 6 and 62 to 72, by which and the mechanism to be hereinafter described, the severed metallic strip is bent around all four sides of the anvil and the ends of the binding strip made to overlap, the binding strip as a whole being held in position to be applied to the box when formed. This may be accomplished in various ways. In the construction shown, the reciprocating frame 168 has a lever 171 pivoted to a stud 172 at opposite sides thereof, and one end of these levers is adapted to engage a stop 173, in this case a bolt, to limit its movement in one direction and at the opposite end of said levers is pivoted a bending jaw or element 174. Each bending jaw is pivoted at 175 to its co-operating lever 171 and said jaw in its normal position, that is in the position shown in full lines in Figs. 6 and 62 receives the binding strip as it is fed forward. Each jaw has a relatively large bearing surface or part 176, in one face of which is inserted a bar 177 forming a continuation of the bar 138 of the reciprocating frame bar 139, said bar having a groove 178 to receive the binding strip and made to conform somewhat to the shape of said strip. A finger 179 is pivoted at 180 to a part of the reciprocating frame 168 on each side thereof and each finger has one end adapted to close a part of the groove 130

178 of the binding jaw so that the strip will be held to move with the jaw and frame. These fingers are normally pressed in one direction by a spring 181, and said fingers have a projecting portion 182 which is adapted as the frame is moved forward toward the anvil or former 169 to engage a fixed cam 183 at the proper time to release the binding strip and permit an independent movement of the bending jaws 174 while bending the strip about the anvil, the action of the finger after it is released being shown in dotted lines in Fig. 65.

Each bending jaw 174 is pivoted at 184, to the bar 139 of the frame 168 and has a recessed portion, as 186, adapted as the frame 168 is moved inward to fit about a boss or socket piece 187 arranged at the corner of the anvil 169 and which serves as a pivot for each of said jaws to swing about the anvil parallel to the sides 188 of said anvil to force the binding metal against the same. There are two jaws 174, one at each side of the frame 168 and these jaws are similarly constructed and operate in a similar manner about the anvil 169 and a description of the one therefore will answer for the description of the other, the operation or movement of the frame 168 with the jaws 174 being set forth more clearly in Figs. 62 to 65. Each jaw 174 is normally held in a certain relative position to that of its coöperating lever 171 and at the same time it should be yieldingly held, otherwise the jaw could not be forced at substantially right angles to the anvil to bend the binding strip. To secure this, a spring 189 is provided, and this spring has one end secured to a part of each jaw 174 and its other end is held to a part of the pivoting stud 175 which is held against movement in the end of the lever 171, the reciprocating frame 168 being provided with a slot 190 to permit a relative movement of the jaw 174 and the levers 171 as the reciprocating frame 168 moves inward.

The inward movement of the reciprocating frame 168 may be accomplished by a rocking lever 191, Figs. 1 and 6, the upper end of which is connected by links 192 to lugs projecting out from the frame 168. The lower end of the lever 191 has a trundle and is operated by a cam 193 on the main drive shaft 45, the said lever 191 being pivoted at 194 on the machine frame. As will be seen when the shaft 45 operates the cam 193 will rock the lever 191 at its pivot and at the proper time will force the frame 168 inward. The bar 139 and jaws 174 carrying the binding strip will move forward until the recessed portions 186 engage the bosses 187 where it is restrained against further inward movement, and the recess 186 of each jaw 174 will engage one of the sockets 187 located at the corner of

the anvil 169 and on further movement of the frame 168 independent of the bar 139 the jaws 174 will be forced about the sides 188 of the anvil or former bending or folding the binding strip about the same. During this inward movement of the frame the fingers 179 will be released from the binding strip before the bending actually takes place, a guide or plate 195, Fig. 6, being arranged in the path of movement of the free ends of the binding strip which projects beyond the outer end of the jaws 174 and serves simply to guide the ends of the strip while the latter is being folded or bent about the anvil.

The anvil, Figs. 62, 72^a, 76, 77, 78, 87, and 87^a, is substantially rectangular in form and is carried by a part of the box-forming mechanism to be hereinafter described, and said anvil conforms to the general shape of the open end of the box to which the binding strip, when completely bent about the anvil is applied to hold the parts of the box together. The particular form of box to be made in the machine shown is square, though the shape may vary, and when square the shape of the anvil is also square. The anvil or former 169 has corner or socket pieces 187 for the front or initial folding and corner pieces 196 and 197 for the back 95 folding or final folding of the strip. These corner pieces may be of hard metal and each has a socket portion to fit its coöperating bending jaw and under each socket portion is a substantially V-shaped part 198 which is intended to give a sharp bend to the binding strip at the corner thereof and to close the corner in order that the package may be substantially square when formed, and said corner pieces are so made that they will not interfere with the placing of the strip upon the box when the latter is formed as will be hereinafter understood when the box forming mechanism is described, the form of the strip when bent being shown in Fig. 109. 100 To bend the strip on the opposite face of the mandrel or back thereof, it is necessary to force the two ends of said strip inward and it is also desirable that the said ends may be made to overlap to provide the 115 proper finish for the article when completed, and to secure this, I provide two oppositely movable folding mechanisms each carrying a pivotal jaw so timed and operated that it will force the free ends of the binding strip about the anvil and at the same time cause them to overlap. This final folding mechanism is shown best in Figs. 66 to 72. There are two rear folding mechanisms 199 and 200. The construction of the folding mechanism 199 is substantially the same as the folding mechanism 200 except as to certain details, and particularly the movement of one of the jaw members and its operation and in so far as the parts correspond, I shall employ the 120 125

same reference numerals and the explanation given as to the operation of the mechanism 200 is also applicable to the operation of the mechanism 199 except as to the differences particularly referred to. The mechanism 200 acts somewhat prior to the mechanism 199 and each of said mechanisms comprises a cross-head 201 suitably guided in the frame, and on this cross-head is held a lever 202 which is pivoted at 203 to the cross-head, and at one end thereof is a stud 204 on which is a trundle 205 which moves in a cam slot 206 on the machine frame. The outer end of the lever 202 has a bending jaw 207 pivoted thereto. A bolt 208 serves as a pivot, and around this bolt is a spring 209 which yieldingly holds the jaw 207 against pivotal movement. The jaw is normally held with its strip-receiving face at right angles to the direction of movement of the lever 202 and in position to engage one of the free ends of the binding strip. The jaw 207 comprises two members 210 and 211, the latter being the one which is pivoted to the lever 202. One end of the member 211 has a laterally projecting lug, as 212, and this lug is adapted to engage a stop 213 on the lever 202, and on the side opposite the toe or part 21 is a projection 214 which is connected by a spring 215 to a lug 216 on the member 210. The purpose of the spring 215 is to hold the members 210 and 211 in their proper relative position but will permit a relative movement between the same through the pivot 217 which serves to hold the two members 210 and 211 together. The jaw member 210 has a recess 218 which is adapted to engage the corner piece 196 of the anvil 169 in a manner quite similar to the jaws 174 and which jaw member is adapted to swing about the rear face or back 219 of the anvil. The cam slot or groove 206 inclines upwardly at the rear so that on the rearward movement of the jaw 207 the said jaw will be forced downward so that the free end of the binding strip while being folded or formed by the jaws 174 will be permitted to move free of the jaw 207 and on the forward movement of the jaw to fold or bend the strip it will be again elevated by reason of the cam groove 206 to a position to cause the strip to enter the opening 220 formed in the face of a bar 221 extending across the member 210 and normally at right angles to the path of movement of the cross-head 201.

The main difference between the bending jaw mechanism 199 and 200 is that the latter is constructed so that it will permit the end of the metallic binding strip on that side to be forced downward below the end of the binding strip of the mechanism 200 and to then force the same upward under the strip in order that the ends may overlap. To secure this result, the outer

member 210 of the mechanism 199 has a part 222 which is held as a part of and moves with a downward and upward swinging forward portion 223 forming the bending portion of the jaw. In the part 223 is a bar 224 having a groove 225 for the reception of the end of the binding strip and this part of the jaw is pivoted at 226, as shown in dotted lines in Fig. 69, and is guided in its vertical swinging movement by a projection or rib 227. The part 227 has a hole 227^a passing therethrough around which is a spring 228 held between the part 227 and nuts 229 on said bolt. A cam 230 carried by a part of the binding strip pinching mechanism to be hereinafter explained is arranged in the path of movement of the jaw as it is forced inward, and the forward portion 223 of the jaw is forced downward against the tension of the spring 228 and in doing so carries with it the free end of the binding strip. As the jaw swings in the arc of a circle as indicated in dotted lines in Fig. 69, the said jaw will pass along under said cam 230 and until said end passes out of the path of the cam when the spring 228 will force it upward again and in doing so will place the bent end of the strip under the preceding strip end which has been bent by the mechanism 200 and in alignment with said end causing the ends of the binding strip to overlap. As the end of the strip is forced up by the spring 228 it is forced into the grip of a spring clip 231 which engages under the binding strip and holds the same to the anvil. The corner 197 of the anvil 169 is slightly different in construction from that of the other corner pieces and this particular corner is shown best in Figs. 87 and 87^a. The construction differs in that there is a cut-away part 232 under the socket portion 197 and above the V-shaped corner 198. The purpose of this cut-away part is to provide clearance for a rearward movement of the mechanism 199 a certain distance to move the part 222 out of the path of the cam 230 so that said part can be returned to its normal position without being again forced downward and during this outward movement the several members of the jaw by their springs will be restored to their normal position or such as shown in full lines in Fig. 69.

The movement of both of the cross-heads 201 by which the bending jaws are forced inward and outward is secured by substantially the same means. The cross-heads 201 are each connected to one end of a rod or link 233 and each link is connected to one end of a rock arm 234 secured to a shaft 235. The shafts 235, Fig. 1, have arms 236 one of which is connected to a rod 237 and the other to a rod 237^a and both rods are connected to links 238. The links 238 are

connected to arms 239 and 239^a pivoted to a part of the machine and said arms carry trundles which are engaged by cams 240 on the main drive shaft 45. The cam 240 for the mechanism 199 is located near the rear end of the machine and the cam for the folding mechanism 200 is located substantially midway of the machine and said cams are so positioned that one will operate the mechanism somewhat in advance of the other, each rod 237 being provided with a turn-buckle 241 to adjust the length of the rod in order that said mechanisms may be operated properly and timed with respect to the movement of other parts of the machine. It will be seen that as the shaft 45 is rotated the cams 240 will move the rods 237 up and down and by reason of the position of the arms 236 the cross-head 201 will be forced inward until the jaws engage the corners of the anvil 169 at which time the said jaws will engage the free ends of the binding strip and will bend the same about the anvil and cause the end to overlap as already described.

The mechanism for forming the binding strip and for holding the same about the anvil having been described, I will now proceed to set forth the means whereby the veneer shooks may be fed to the machine and made into box form and applied to the metallic binding strip while it is held on the anvil.

In Figs. 2, 3, 5 and 6 and in larger detail in Figs. 7 to 26 is shown one means whereby the shooks may be held in a plurality of magazines and automatically fed vertically upward in position to be removed therefrom by suitable mechanism which will be hereinafter described. As shown, there are two magazines 242 and 243 arranged at the rear and at one side of the machine frame. These magazines are similarly constructed and are arranged at an angle with respect to the longitudinal center of the machine and each 45 magazine has a frame member 244 which is securely bolted to the machine frame. The frame member 244 has a follower 245 adapted to move vertically therein, and said follower 245 forms a support for the veneer shooks 244^a. The follower is provided with a slide portion 246 which is adapted to move vertically in the guides 247 which are secured within a recessed part of the magazine frame member 244 by means of screws 248. 50 A detachable shook-holding member 249, Fig. 24, is detachably held to each magazine frame member 244 so that said holder may be readily attached to or detached from the magazine frame 244 to supply new shooks as they are exhausted by being fed to the machine. This holder 249 is substantially U-shaped in form so as to inclose the shooks and has its body portion 250 of sheet steel or other metal provided with angle irons

251 for strengthening purposes, and substantially U-shaped bars 252 at the upper and lower portion thereof also for strengthening purposes. At the inner ends of the shook-holding member 249 are angle irons 253 extending the entire length of the magazine, a part of which projects below the lower bars 252, and secured to the sides of the member 249 are plates 254 which serve to support the shooks temporarily within the holder until the same have been placed within the frame member 244 and over the follower 245. The frame member 244 is provided with supports 255 at opposite corners thereof which provide spaces 255^a, Fig. 8, into which is adapted to be seated the angular ends 256 of the magazine holder member 249. The upper portion of the holding member 249 is held against accidental displacement while in working position and in such a way as to be readily detached therefrom by means of pivotally held spring arms or levers 257. The levers 257 are pivoted at 258 in forked guides or brackets 259 and 259^a located on opposite sides of the magazine frame member 244 and each lever 257 has a tooth 260 which engages the edge of one of the angle irons 253, a spring 260^a being provided to keep the lever catches in engaging position. The magazine holder member 249 may be readily placed with its open side against the inner face of the frame member 244 and between the guides 259 and 259^a and when held in the position shown the said holder will be detachably held as a part of the magazine 100 and the shooks may be made to rest upon the follower 245.

The follower in its lowest position is below the point where the shooks are supported by the plates 254, and it then becomes necessary to raise the follower of each magazine until the follower engages the lowest shook. To do this quickly, a shaft 261, Figs. 21 and 22, is located convenient to the magazines and on this shaft is an operating handle or lever 261^a. The shaft 261 is suitably supported in brackets 262 and fixed to the shaft 261 is a sleeve or collar 263 which has clutch teeth 264 and 265 on opposite faces thereof. The clutch teeth 264 are adapted to engage the clutch teeth 266 on the boss 267 of a lever or arm 268, the outer end of which carries a roller or trundle 269 which is adapted to engage under a projecting part of one of the followers, as a part 270, to elevate said follower of one of the magazines while the teeth 265 engage teeth 271 of the boss 272 of a lever 273 extending in an opposite direction to that of the lever 268 and on which is a trundle or roll 274 adapted to engage the follower of the other magazine. These levers 268 and 273 are each pivoted on the shaft 261, and are each normally held in a

lowered position by a spring 275, one end of which spring is securely held to a projecting part of each of said levers. It will be seen that when the lever 261^a is moved 5 in one direction, as that indicated in dotted lines in Fig. 22, the clutch teeth 264 of the collar 263 will engage the teeth on the boss 267 of lever 268 and will move the same therewith and thereby the follower within 10 the magazine coöoperating with the arm 268. During this movement of the lever, owing to the spacing of the teeth, the arm 273 is not operated, but by moving the lever in the opposite direction the teeth 265 of the collar 263 will engage the teeth 271 formed on 15 one face of the arm 273 and through the roll 274 will elevate the follower in the other magazine. The shooks will thus be raised in either of the magazines from their initial 20 support on the plates 254 of the frame holder 249 and will be supported on the follower, in order that all the shooks may be raised or fed upward by the follower in either of 25 the magazines.

To feed the shooks upward in either of the magazines each of said magazines is provided with a screw 276 which is rotatably held in the magazine frame member 244. The screw 276 has an upper threaded 30 portion 277 for a purpose to be hereinafter described, and a lower threaded portion 278. The lower threaded portion 278 is engaged by the threaded ends 279 of a device 280 forming substantially a split nut. 35 The threaded end 279 is formed as part of two lever members 281 and 282, and each of these lever members are pivoted at 283 to a part of the follower, and said ends 279 are normally forced toward each other 40 to cause the threaded portions to engage the threads 278 by means of a spring 284 the ends of which surround lugs 285 extending inward from each of the lever members 281 and 282, each lever member having a 45 handle portion 286 by which the lever members may be moved on their pivots. It will be readily seen that in their normal position, when the threaded portion 279 engages the threaded part 278 of the screw 276, the 50 follower will be raised within the magazine when the said screw is rotated, and by manually forcing the handle portion 286 toward each other the threaded portion 279 will be released from the screw so that the follower may 55 be lowered, which it will readily do owing to its weight, and when the gripping parts 286 are released the spring 284 will force the threaded ends 279 again into engagement with the threaded part 278 of the screw, 60 so that when the screw is rotated as will be presently described, it will again move each follower upward within its magazine.

The threaded part 277 of each screw 276, the screw of each magazine as well as the 65 other parts thereof being substantially the same, is spaced from the part 278 to provide a part 287 on which there is no thread, so that when the follower reaches the point where the threaded ends 279 of the follower feed nut passes beyond the thread 278 into 70 the space 287 the said follower will cease to move upward even if the screw is rotated. At this time the top surface of the follower is above the plane of movement of two pivotally held arms 288 and 289. These arms 75 are pivoted on the rods 289^a and these arms are supported upon an independently movable frame 290 forming a part of a supplemental feed 291, the purpose of this feed being to continue to feed the shooks within 80 the magazine independent of the follower 245 and until a new magazine holder full of shooks has been again placed in position to recharge the magazine. The supplemental feed frame 290 is located at the rear of the 85 magazine frame and at the upper portion thereof, and said frame has a part 291^a which is held to move vertically in the guides 292 located on opposite sides of the feed screw 276. A lever 293 is pivoted at 90 294 adjacent to the feed screw 276 and on the feed frame 290 and this lever 293 has a threaded part 294^a at one end and a segmental gear 295 at the other end. The teeth 295 are in mesh with similar teeth on an 95 arm 296, Figs. 7 and 11, of the pivotal arm 289 so that when the arm is moved in one direction it will throw the threaded portion 294^a out of engagement with the screw and on movement in the opposite direction will 100 cause the threaded portion 294^a to engage the screw and thereby move the frame together with the pivotal arms 288 and 289 upward to feed the shooks. When the follower 105 245 is in operation the arms 288 and 289 should be out of the path of the follower and the shooks and in the position shown in dotted lines in Fig. 11. This is secured by forming on the main frame member of the 110 magazine a recessed or cut-away part 297 on each side of the magazine against the solid portion of which the inner edge 299 of each of the pivoted arms 288 and 289 are adapted to rest and which holds the said arms in the position shown in dotted lines. 115 When the follower 245 is about to become disengaged from the threads 278 of the feed screw, the frame 290 is elevated a sufficient distance by the engagement of the part 299^a with a part of the supplemental feed frame 120 to release the edges 299 of the pivoted arms 288 and 289 from the solid portion of the magazine frame member, at which time the said arms will move inward through 125 openings 300 formed in the sides of the magazine frame member which openings extend to the top of the magazine so that the frame member and arms may move upward to carry the shooks supported thereby. The follower is cut-away at 301 to permit the 130

arms 288 and 289 to pass under the shooks and engage the latter and to permit the follower to be lowered to the lower part of the magazine in position to again feed the shooks upward when the new magazine holder is placed in position, the said arms 288 and 289 being normally forced inward by means of springs 302 arranged around the rods 289^a. By this means the shooks are fed upward part of the distance by the follower 245 of each magazine and when at a certain point and before the entire supply is exhausted the supplemental feed is thrown into operation which continues to move the remaining shooks upward through the magazine until it can be again charged with a new supply held in the magazine holding member, the said supplemental feed being lowered into position again by moving of the arms 288 and 289 outward until the arms again engage the solid portion or grooves 297 of the magazine frame member, as shown best in Fig. 12^a.

The upper portion of each magazine is provided with a plurality of fingers 303. These fingers are located at the upper portion of the frame member near the corners thereof and are adapted to engage the shooks so as to hold the same substantially independent. These fingers are pivoted at 304 to rods 305 and to two of these rods are held links 306, the links at one side of each magazine being connected by a rod 307 so that said fingers 303 will move together either inward or outward according to the width of the shook and will center the shook in its proper place. The shooks will be forced rearward by the two front fingers and the two outer side fingers are connected together to center the shooks by engagement with their ends. Each finger at its upper edge is provided with a series of serrations 308 tending to keep the shooks separated, and at its lower end has a recessed portion 309 adapted to receive a spring 310 which normally forces the teeth 308 inward, and the purpose of the fingers is to prevent more than one shook being fed at one time.

To rotate the feed screw 276 of each magazine and to automatically control the feed through the upper shooks of each magazine various means may be employed. As shown, each feed screw has a disk 311 which is provided with a flange 312, and said disk is rigidly fastened to the screw and is held against upward movement by an angular plate 312^a. A lever 313 is pivotally held to the lower part of the feed screw 276 to rock independently of said feed screw, and this lever is forced in one direction by a spring 313^a, Fig. 10, and is limited in this movement by a bolt 313^b. The lever adjacent to the screw has recesses 314 in which are loosely seated the ends 315 of friction dogs 316. These dogs 316 have slots 317 where-

by the dogs may be made to span the flange 312, and connected to the dogs are the springs 318 one end of each spring being held to a post or pin 319, the clutch operating substantially the same as the clutch for 70 rotating the feed rolls 97 and 98. It will be seen that when the arm 313 is rocked in one direction the dogs will move free of the flange 312 but when said arm is moved in the opposite direction the dogs will grip the 75 flange of the disk 311 and will impart a like movement to the feed screw.

A reciprocatory bar 320 is located adjacent to the magazines and held to this bar are pawls or dogs 321 and 321^a. Each 80 dog is pivoted at 322 to the bar and has its other end in the form of a tooth 323 which is adapted when the bar 320 is reciprocated and the said dog depressed to engage a roll 324 carried by the outer end of each of the 85 feed screw operating levers or arms 313. The dogs 321 are normally forced upward by a spring 325 arranged around a bolt 326 and the tension of said spring may be varied by nuts 327 or otherwise. The bar 320 90 is normally forced in one direction by a spring 328, Figs. 25 and 26, and carried by said bar is a projection carrying a pin fitting into a bearing or box 329 which is adapted to fit in the slotted end of a lever 95 330. This lever 330 is pivoted to a shaft 331 and on the outer end of said lever is a trundle or roll 332 which is adapted to be engaged by a cam 333 located on the main vertical drive shaft 334, the said shaft 334 100 being provided at its lower end with a miter gear 335 which is in mesh with a similar gear 336 secured to the shaft 45, as shown in Fig. 1.

As the thickness of the shooks may vary 105 and to prevent crowding of the shooks at the upper part of the magazine against the shook-removing mechanism and in order that the shooks may be removed one at a time, I provide automatic means controlled by the 110 height of the shooks which will regulate the operation of the feed screws to permit the same to operate according as to whether or not the shooks are fed properly. To secure this, a plate 337 is arranged at the upper 115 part of each magazine against which the upper shook may press and this plate is connected to a slideable rod 338 which is bent intermediate its ends where it is pivoted to a link or crank 339. This crank is pivoted at 340 to forked brackets extending outward from the magazine frame member 244 so that when the rod 338 is up the said crank will move the plate 337 upward and outward. The rod 338 is also connected to 120 a crank 341, one for each magazine, and said cranks are connected one to a shaft 342 and the other to a shaft 343. The shaft 343 is located between the feed screw arms 313 and the shaft 342 at one side of one of said 125 130

arms, and carried by the shaft 342 is an arm 344 while on the shaft 343 is an arm 345 in the outer end of each of which is a roll 346.

The shaft 343 is provided with an arm 347 to which is pivotally held a rod 348 on which is fixed a collar 349. The free end of the rod 348 is provided with a collar 350 and slidably upon the rod is a sleeve 351. A spring 352 is interposed between the collar 350 and one end of the sleeve 351 and said spring tends normally to force the rod 348 lengthwise of the sleeve and the collar 350 away from said sleeve. An arm 353 is held to the shaft 342 at one end thereof and pivotally connected to said arm is a rod 354. This rod 354 has a collar 355 secured thereto and said rod is connected to the crank arm 353 by a ball and socket joint, as at 356. A collar 357 is secured to the outer end of the rod 354 and slidable on the rod between the collars 355 and 357 is a sleeve 358, spring 358^a being arranged around the rod 354 between the collar 355 and the sleeve 358. The sleeves 351 and 358 are pivotally held to a rocking arm 359 in any desired way and this arm is held to a shaft 360. An arm 361 projects from the shaft 360 and connected to the outer end of this arm is a rod 362, the upper end of which is connected to a lever 363 which is operated in a manner to be hereinafter described.

It will be seen when the bar or rod 320 is reciprocated through the lever 330 and cam 333 that the dogs 321 and 321^a mounted on said bar will also be reciprocated. The rod 362 through the lever 363 will be given an up-and-down movement and this will rock the shaft 360 and arm 359. This rocking movement of the arm 359 will reciprocate the sleeves 351 and 358 and through the springs 352 and 358^a will yieldingly force the rods on which the sleeves slide to rock the shafts 343 and 342 which will force the arms 345 and 344, respectively, downward, causing the pawls coöperating with said arms to engage the rolls of the feed screw arms 313 and thereby force the followers upward in the magazines. At the same time that this is taking place through the engagement of the rolls 346 with the dogs, the shafts 342 and 343 will operate the cranks 341 which will force the rods 338 downward at each reciprocation of the rods 348 and 354. As each rod 338 is connected to a shook-engaging plate 337 the latter will be moved downward and inward with the downward movement of each rod 338 to engage the uppermost shook. If the feed has been too rapid and the shooks begin to crowd at the upper end of either of the magazines, the plate 337 cannot descend as far as it otherwise would and this will hold one of the shafts 342 and 343 against further movement according to which mag-

azine contains the crowded shooks. If the shaft 343, for example, is held against further movement by reason of the crowding of the shooks the sleeve 351 can reciprocate on the rod 348 by reason of the spring 352 ⁷⁰ without operating the arm 347. This will cause the coöperating roll 346 carried by the arm 345 to remain out of the path of the dog 321 so that the reciprocation of the bar 320 may continue without operating ⁷⁵ its coöperating feed screw arm 313 thus stopping the feed of the particular magazine in which the shooks have been fed too rapidly. As soon as the position of the uppermost shook is proper and the feed normal the ⁸⁰ plate 337 of that magazine will be permitted to lower far enough during the reciprocation of the rod 338 coöperating therewith to cause the roll 346 of the arm 345 to force the dog 321 into engagement with its feed screw arm to again start the feed. It will be understood, of course, that the crowding in the other magazine will be similarly prevented through the rod 354 and that the feed may be automatically stopped in either ⁸⁵ or both magazines in the manner described.

As the shooks are fed upward in the magazines they are automatically removed therefrom one at a time and these shooks are placed crosswise with respect to each ⁹⁵ other in a rotary carrier or turret, and by the carrier the shooks in crosswise position will be moved in the path of die mechanism which bends the shooks into box form ready to have the binding strip, previously ¹⁰⁰ deformed and held to the anvil, as already described, applied thereto. As one means for removing the shooks, I provide a rotary and reciprocatory device 365, Figs. 2, 27 to 32, having means to raise the shooks one at a ¹⁰⁵ time and in succession from the magazines. The head 365^a has three tubular arms 366 bolted thereto and radially arranged and these arms are similarly constructed so that a description of one will answer for the ¹¹⁰ others. Each tubular arm is provided with a flange 367 which is bolted by screws 368 or otherwise to the head 365^a at equal distances apart and on the outer end of said arm is a pneumatic head 369. This head is constructed to remove one of the shooks from one of the magazines and when rotated and placed over the next magazine it will also lift a shook from the second magazine so that one shook will lie crosswise of ¹²⁰ the other owing to the rotary movement of the device 365 and also the position of the shook magazines with respect to said heads. The head 369 carries a plurality of pneumatic cup-like devices 370 and 371. Each of ¹²⁵ these devices is made of flexible material, as rubber, to provide a suction device, and each has a holding nipple 372 of tubular form which communicates with the tubular arm so that suction may be created, and ¹³⁰

when the suction cups or devices are forced against the shooks, as will be presently described, the said shooks will be held thereto until the suction is again released. The devices 370 are intended for the shooks of one of the magazines, and the devices 371 for the shooks of the other magazine, and the suction in each set of devices is independently controlled so that the action of one will not affect that of the other, the engaging surface of the devices 377 being somewhat lower than the engaging surface of the devices 370 according to the thickness of the shooks so that the devices 370 may first engage the shooks of one magazine and the devices 371 properly engage the shooks of the next magazine without at all interfering with each other and so that the shooks will lie close against each other while so held by each head.

The heads act upon the shooks in the magazine in a similar manner but in succession and each of the arms 366 has two chambers 373 and 374. The chamber 374 is controlled by a valve 375 which is held to a rod or stem 376. This valve 375 has a seat in a bushing 377 held to the tubular arm, and resting against the bushing is a spring 378, one end of which rests against a collar 379 adjustably held by screw threads or otherwise to the valve stem or rod 376 and tends normally to force the valve 375 to its seat 377. The outer end of the valve stem 376 is held to slide in a sleeve 380 the outer end of which latter is guided in a recess 381 in a cap 382 secured by threads to the outer end of the tubular arm 366. The sleeve 380 is provided with a collar 380^a between which and a nut 380^b is a valve 383 which is adapted to engage a seat in the bushing 384, said valve serving to control the suction in the chamber 373. The valve 383 is normally held to its seat by a spring 385 one end of which rests against a collar 380^a and its other end is seated in a recess in the cap 382. As will be seen when the rod or stem 376 is forced outward the valve 375 will be moved away from its seat and forms a communication through a passage to a chamber 386 within the head 365^a. The chamber 386 communicates with an exhaust pump or other means for creating suction in a manner to be presently described, and when suction is created in the chamber 374 the said chamber owing to its communication with the suction cups 370 through the common chamber 387 will cause one of the shooks in one of the magazines to be held by the devices 370 and when the head is moved into position over the next magazine, the valve stem 376 will be moved a further distance and this will cause the outer face of the collar 375 to engage the inner end of the sleeve 380 which will open the valve 383 causing a communication be-

tween the tubular head through the passage-way 388 and the chamber 373 and from there direct to the chamber 386 of the head 365^a.

The head 365^a with its arms should be not only lowered to engage the shooks in the magazines but must be raised to lift the shooks therefrom and also must have a rotary movement imparted thereto, timed with respect to the movement of the shook feed mechanism of the machine. At the proper time the valves of each arm are automatically operated to cause the shooks to be held thereto, and after a shook has been removed from each magazine by one of the heads the said shooks in a crosswise position must have the suction so controlled as to simultaneously discharge the shooks from the heads 369. To accomplish this reciprocatory movement of the pneumatic device as well as its rotary movement and also to intermittently rotate the device, I secure the head 365^a to a tubular shaft 389. This shaft 389 is vertically arranged and is secured to the head 365^a by a tubular cap 390, Fig. 29, the said head being provided with a removable plug 391 for access to the said cap and the interior of the head. The shaft 389 is held to rotate and also to reciprocate in the boss 392 forming a part of the machine frame, and at the lower end of the shaft is a nipple or coupling member 393 of any suitable construction to which may be attached a flexible hose or pipe 394 leading to a suitable exhaust apparatus. The coupling 393 is held to a rock arm 395 and this rock arm is held to a shaft 396 and formed integral with an arm 395 is a second arm 397. This arm 397 is connected by a rod 398 to the outer end of a lever 399. The lever 399 is pivoted at 400, Figs. 31 and 32, and one end of said lever 399 carries a trundle 401 which is engaged by a cam 402 secured to the main vertical drive shaft 334, so that when said shaft 334 is rotated, it will rock the lever 399 and through the rod 398 and arms 397 and 395 will cause a vertical movement to be imparted to the tubular shaft 389, the said shaft and parts being restored to their normal position either through the weight of the pneumatic device or by a separate spring or springs, if desired, which may be provided for that purpose. The tubular shaft is thus moved upward and downward to carry the pneumatic device, and to cause the pneumatic heads 369 to pass into the magazines and also to remove the shooks one at a time therefrom. When one of the shooks has been removed, that is by the suction cups 370, the entire device is given an intermittent rotary movement to carry the pneumatic head over the next magazine and said head is again lowered into that magazine to cause the suction cups 371 to engage the uppermost shook in 130

said second magazine to remove the same therefrom. This rotary movement of the tubular shaft 389 with its pneumatic device is effected through a gear 403 which is secured to the shaft 389 and this gear is in mesh with a larger gear 404 rotatably held on a shaft or stud 405. The gear 404 has its face wide enough to permit a vertical movement of the gear 403 with the shaft 389 and still be rotated thereby, and meshing with the gear 404 is a gear 405^a which is held to a carrier or turret shaft 406. This shaft 406 Figs. 40 and 41, is given an intermittent movement by a modified Geneva movement 407. This movement comprises two members 408 and 409, the latter being secured to the shaft 406 and the former to the machine bed or frame. This movement differs from the ordinary form of Geneva movement in that the trundle 410 which alternately engages the slots 411 is movable radially by a block or slide 412, one end of which carries a trundle 413 movable in a cam groove 414. The member 408 has a radial peripheral surface to engage the surface 414^a for locking purposes and the reason for moving the trundle 410 inward and outward is that a more uniform rotary movement is thereby secured to the shaft 406, as the said trundle 410 is moved near or farther from the center during the rotary movement of the member 408, and while this form of movement is preferred any other movement may be employed.

It will be seen that the arm 363 for operating the rod 362 of the shook feed mechanism is integral with the arm 397 of the pneumatic transfer means and therefore simultaneously operated by the same cam and timed with relation to each other.

Each valve stem 376 of the pneumatic shook transfer device must be operated at the proper time and with relation to the movement of said device, and to accomplish this the inner end of each valve stem is normally held in contact with an arm 415. Each arm 415 is secured to a vertically arranged shaft 416, Figs. 27, 29, 38 and 39, and on the lower end of each shaft 416 is an arm 417 one end of which carries a trundle 418. The trundles 418 are adapted to be engaged by a shifttable cam 419, Figs. 38 and 39, which is held to rotate independently on the tubular pneumatic transfer device shaft 389. This cam is so shaped that it will operate the arms to open the valves 375 and 383 at the proper time and to shift said cam at the proper time is an arm 420 to which is connected one end of a rod 421. This rod 421 is connected to an arm 422, and this arm is connected to oscillate with an arm 423, one end of which latter arm is provided with a trundle 424 which engages a cam slot 425 of a cam 426 held to the main vertical drive shaft 334. As the shaft 334

rotates it will rotate the cam 426 and through it move the rod 421 and shift the position of the cam 419 relatively with respect to the position of the pneumatic transfer head and through the arms 417, shafts 416 and arms 415 within the tubular head force the proper stem or stems 376 outward at the proper time to open the valves or permit the said valves to close according to whether the shooks are being transferred by said device or to be discharged therefrom.

The shooks as they are transferred by the pneumatic transfer device in cross-wise relation, that is one taken from one of the magazines and held by the devices 370 and the other at right angles thereto and taken from the second magazine by the suction devices 371, are moved one-third of a rotation over a transfer carrier 427 into which the shooks are discharged. This carrier is in the form of a turret and has four shook receivers 428, 429, 430 and 431. These receivers are radially arranged upon a turret or wheel member 432 which is secured to the upper end of the vertical shaft 406, the latter being rotated from the main vertical shaft 334 as already described and as shown best in Figs. 40 and 41. A carrier frame or member 432 has four receiver frames 433 bolted thereto. Each of these frames has a circular flange portion 434 and projecting inward therefrom are lugs to which are pivotally held supporting elements or members 435, 436, 437 and 438. These elements have angularly formed portions forming a seat for the outer ends of the shooks and the elements 437 and 435 are opposed to each other and support one shook, as 439, while the shook 440, Fig. 33, is supported between the elements 438 and 436. A shaft 441 is journaled in the frame under the shook supporting element 437 to which the latter is held by lugs or otherwise so as to have an oscillatory movement with said shaft, and under the shook supporting element 435 is a similar shaft 442 which is journaled in the receiver frame and has the element 435 held to oscillate therewith as by lugs projecting beneath the supporting portion of said element. One end of the shaft 441 is provided with a crank arm 443 extending downward therefrom, and the shaft 442 has a crank arm 444 extending upward, the crank arms being connected by a rod 445. The rod 445 is provided with a collar 446 and normally forcing the collar and rod in one direction is a spring 447 which has one end bearing against a projection on the carrier and tends normally to force the arm 443 in one direction to shift the position of the elements 435 and 437. The elements 436 and 438 are located at right angles to the shook supporting elements 435 and 437 and the element 436 has an extension 448 while the element

438 has an extension 449. These extensions 448 and 449 together with the elements are suitably supported to swing in bearings on a part of the receiver frame of the carrier, 5 and to the part 448 is held an arm 450 in line with its pivot and projecting upward, while from the extension 449 is an arm 451 extending downward therefrom. The arms 450 and 451 are connected by a rod 452 and 10 this rod is provided with a collar 453. A spring 454 is arranged around the rod 452 between the collar 453 and a projection 455, Fig. 33, and serves normally to force the elements 436 and 438 to a closed position to receive the shocks as they are discharged from 15 one of the arms of the pneumatic transfer device 365.

As soon as the supporting elements 435 to 438 receive the shocks, the said elements are 20 moved on their pivots to aline the shocks and to hold them properly prior to the same being formed into box shape and to operate said elements the arm 444 to which the rod 445 is pivoted is extended and carries a 25 trundle 456, Fig. 36, which is adapted to be operated by a cam or cams 457 held to move on the shaft 406 independently thereof. The cams 457 are movable with an arm 458, and said cams are secured to the boss 30 of said arm and are adapted to operate the shafts of the carrier alining elements of each of the shock receivers. The outer end of the arm 458 is connected by a rod 459, which may be adjustable by a turn-buckle 35 460, to an arm 461 which is operated through the arm 423 and the cam 426 to be shifted relatively to the position of the carrier and its receivers 429 to 431, in order that the 40 said shock supporting elements may be operated with a movement inward to properly aline the shocks and while the carrier is stationary.

In receiving the shocks from the picker or pneumatic transfer device, the rock cam 457 opens the shock holding chairs or elements 435 to 438 and this action compresses the springs 447 and 454. When the picker or pneumatic transfer device descends the rock cam makes a movement to the right a 50 part of a revolution, thus allowing and depending upon the springs 447 and 454 to close the chairs or elements on the shocks and properly center them; while diametrically opposite to the foregoing part of the 55 cam 457 the said cam is forcibly opening the elements or chairs 435 to 438 against the action of springs 447 and 454 but not until after the two shock folding members have hold of the shocks as will be herein-after described.

The shocks while held by the carrier are moved therewith so as to be interposed between the plunger element 463 and the die element 464 of the box-forming mechanism. The plunger element is normally located

above the carrier, and the die element 464 and mechanism is located under the same, and the latter element is of such form that it may be moved upward through one of the receivers of the carrier in which the crossed shocks are located, both plunger mechanism and die mechanism being adapted to move toward each other. The plunger mechanism 463 comprises a head 465 and a tubular stem portion 466, the upper end of 70 which has a collar 467 secured thereto. This plunger sleeve is provided with a key-way which is engaged by a key 468 held to a part of the machine frame so that the said sleeve may reciprocate up and down and be held against rotary movement, and interposed between the boss 469 and the collar 467 is a spring 470. A rod 471 is movable independent within the sleeve or shaft 466 and on the lower end of this shaft is a pressure foot 472. This pressure foot is substantially rectangular in form and corresponds to the size of the bottom of the box to be made. The pressure foot is held rigidly to the lower end of the rod 471 and said pressure foot is adapted to be forced downward independent of the plunger of which it forms a part, and is adapted to rest upon the shocks in the carrier. At this time the die mechanism 464 is forced upward under 95 the shocks to meet the pressure foot and the pressure foot and the die mechanism moved together removing the shocks from the carrier to a point above the same.

The die mechanism, Figs. 89 to 94 and 100 99 to 102, comprises a frame or head 473 which is secured to the upper end of a rod 474, said rod being vertically movable in a manner to be hereinafter described. The rod 474 has a cap-plate 475 secured thereto 105 by screws or otherwise and said plate is substantially rectangular in form and is provided with downwardly-extending ribs 476 forming a pivot for the yielding plates 477. There are four plates 477 and each 110 of these plates has a portion 478 which extends within a recess or space formed under the cap-plate 475 and said plates are each normally forced upward by two or more springs 479, the said cap-plate 475 and the 115 yielding plates 477 serving to form a support for the bottom of the basket while being folded and said plates 477 allow for unevenness in the length of the shocks. There are four folding sides or plates 480, 120 481, 482 and 483, as shown best in Fig. 89. These plates or folding members are substantially the same width as the shocks and are intended to force the ends of the shocks upward while held between the presser foot 125 472 and the bottom plate 475 with its yielding members 477, and said folding members cooperate with the plunger and serve to form the shocks box-shape. The sides 480 to 483 are each provided with slots 483 in

which boxes or bushings 484 on the studs 485 are adapted to slide. These studs 485 and bushings 484 are carried by a pivotally held block 486. There is a block 486 for each folding plate or side member and these blocks are pivotally held to shafts 487 and are adapted to move upward with their cooperating folding sides or plates, and said blocks and the folding plates in their upward movement have a slight relative movement with respect to each other. Each block has a shaft 488 and pivotally held to this shaft is a lever 489, shown in detail in Fig. 96, and each lever has jaws 490 formed with slots 491 adapted to receive blocks carried by studs 492 on each of the folding side plates or members 480 to 483. The levers 489 have an arm 493 projecting inward therefrom on the outer end of which is a stud 494 and on this stud is a trundle 495. The trundles 495 are adapted to engage cam grooves 496 arranged in a part of the die head 473. The inner ends of each folding plate or side bears against the outer edge of the yielding bottom members 477 and said bottom members have parts 497 which enter recesses in the end of the said plates to prevent lateral movement and said folding side plates and bottom plates or members form a joint which will fold the shooks to form a substantially square bottom as best shown in Figs. 101 and 102. The folding side plates have parts 498 fitting into recesses 498^a in the blocks 486 to further guide the same in their upward movement, said recesses being located in the bearing portion 499 of said blocks. A spring-pressed pin 499^a is held in an opening located adjacent the recesses 498^a and said pins are adapted to bear against the folding plates to permit the latter to yield slightly when folding the shooks box shape. The pins are pressed outward by springs and these may have their tension varied by nuts 499^b against which one end of the springs rest. Each of the blocks as well as the levers 489 through the stud or shaft 488 is connected by a link 500 to a vertically movable frame 501. This frame may be rectangular or circular in form and has cut-away portions to which the links 500 are pivoted, and said vertically movable frame is held to slide between guides 502 forming a part of the machine frame or as a part of a supporting frame 503 held within an opening of the main machine frame. The lower part of the vertically movable frame member of the die mechanism is provided with portions 504 to which are connected one end of the links 505. There are two links 505 and the lower end of said links are connected to levers 506 which are pivotally held on the shaft 507, and projecting outward from said shaft are arms 508. The arm 508 is connected to a rod 509 and this rod may be adjustable

through a turn buckle 510. The rod 509 is pivotally held to an arm 511, one end of which is pivoted at 512 to a bracket 513 secured to a part of the machine frame, and on said lever is a trundle 514 which enters a groove in a cam 515 located on the main drive shaft 45. As the drive shaft is rotated the arm 508 will raise the links 505 and through the frame 501 and links 500 cause the side folding plates 480 to 483 and blocks 486 to move upward, the levers 489 being guided at their free ends by means of the trundles or rollers 495 engaging the cam grooves in which they work as already described. 70

The entire die mechanism or head is moved upward and this is accomplished through links 516 which are pivotally held to a part of the die head 473, and these links are pivoted at their lower ends to arms 517. An arm 518 is pivotally held to the shaft 507 and on the outer end of this arm is a rod 519 which may be adjustable lengthwise by a turn buckle 520. The lower end of the rod 519 is pivotally held to an arm 521 which is pivoted at one end to the shaft 512 in a manner similar to the arm 511 and on the arm 521 is a trundle or roller 522 which is adapted to be operated by a cam 523 also secured to the main drive shaft 45. It will be seen that as the main drive shaft is rotated and the cams 515 and 523 are rotated, an upward movement will be given to the entire die head and during this movement a relative movement will be imparted to the reciprocating frame 501 so as to move the folding plates or sides 480 to 483 on their pivots to fold the sides of the box and during the upward movement the box thus folded will move with the presser foot 472, the said presser foot being operated positively by the same mechanism by which it is lowered or forced downward to initially engage the surface of the shooks while held in the transfer mechanism or not as desired. 95

The upper end of the presser foot rod 471 is provided with a collar 524 which is held thereto by a thread and a nut 525, locking it in position, and engaging the collar are studs 526 projecting inward from the bifurcated end of a lever 527. This lever 527 is pivoted at 528 to a bracket 529 extending upward from the frame, Fig. 1, and the outer end of the lever 527 is connected to a two-part rod 530. This two-part rod is constructed to have a yielding connection between the parts thereof as by a spring 531 so that the lever 527 may be moved on its pivot in such a way that when the presser foot 472 engages the shooks, a yielding connection may be provided. The rod 530 at its lower end may be connected to an arm 532 fastened to a shaft 532^a and held in said shaft is a lever 532^b which is operated by a cam 533 or otherwise to recipro- 110

cate said rod and to move the rod 471 and presser foot upward and downward.

The sleeve 466 carries at the lower end thereof the plunger head 465 which may be formed integral therewith and said plunger head has a recessed portion to which the anvil serving as a former for the binding strip is secured, the said plunger portion extending slightly beyond the anvil so as to provide a bearing surface for the upper part of said binding strip. At each side of the plunger head is pivotally held a former plate or member 535. These former plates, Figs. 73, 79 to 88, have a straight surface 536 against which the side of the box when formed by the dies is adapted to rest, said plunger being adapted to fit within the box, and each former plate 535 has an inner hooked part 537 substantially midway thereof which is adapted to fit over a rod or stud 538 to adapt each side to move with the rod as a pivot and to conform to the shape of the box. Each former plate has projecting parts 539 to engage a part of the plunger head, the corners of which are extended, as at 540, Fig. 82. Each former plate has a recess 541 at the upper part thereof to receive the head of a screw 542 the threaded end of which engages a part of the plunger head, said screw serving to limit the outward movement of the upper portion of the former plate. At each side of the screw 542 is a spring 543 one end of which is located in a recess in the former plate and the other end fits about the head of a screw 544 by which the tension of the spring may be varied, the springs 543 serving to yieldingly force the upper ends of the plunger former plates outward. By pivoting the said plates in the manner shown, they will conform to the angle of inclination of the box and will form a bearing surface for the inner portion of the box when the die-forming plates 480 to 483 are forced to bend the shooks into box form, so that the said shooks as they are bent are properly held ready to receive the binding strip which is already supported around the anvil located above the upper edge of the box, as shown best in Figs. 101 and 102.

As the box properly formed and held is forced farther upward by the upward movement of the die mechanism the upper edges of said box will enter the binding strip and at this time the binding strip is pressed on to the upper edge of the box to be clenched and held thereto to properly bind and hold the bent veneer shooks in box form. This may be accomplished in various ways. As one means for clenching the binding strip to the box form, I provide a plurality of clenching blades 545 which are secured to the lower end of the rocking levers 546, 547, 548 and 549. Each blade 545 has a relatively long surface, Figs. 79, 80 and 81, and each

blade is provided with a plurality of slots 550. Passing through the slots of each blade are bolts 551, the threaded ends of which are secured to the lower end of one of the levers, and at the rear of each lever is a plurality of screws or bolts 552 by which the clenching blades 545 may be adjusted. There are two or more spring plates 553 which tend to force each plate 553 past the edge of its coöperating clenching blade to form a ledge for the binding strip to rest on while being clenched to the box body. When the rocking levers 546 to 549 are moved inward, the plates 553 will engage the side of the box body and will yield to allow the clenching blades to continue inward to bind the metal strip about the box body. The levers 546 to 549 have arms 554 extending upward therefrom and these arms are yieldingly held together in pairs by means of diagonally arranged springs 555. Each lever 546 to 549 has its upper end provided with a recess or socket, and fitting this socket is one end of a link 556, the lower end of which fits a socket 557 forming a pivotal connection between the upper end of the levers 546 to 549 and a vertically movable sleeve or collar 558 in which are the sockets 557. The collar 558 is vertically movable on the sleeve 466 and at the upper end is substantially square in form and provided with grooves 559 in which are the slide blocks 560, the latter being secured to studs 561 extending inward from the bifurcated end 562 of a rock lever 563, shown best in Fig. 1. This lever 563 is pivotally held to a shaft 564 and the outer end of said lever is connected by a rod 565 to an arm 566, the outer end of which carries a trundle 567 which engages a cam groove in the cam 568 carried by the main drive shaft 45. When the shaft 45 operates the cam 568 will oscillate the lever 563 and through the collar 558 will cause the clenching levers 546 to 549 to move on their pivot shafts carried by brackets supported on the machine frame, and this movement through the links 556 will cause the blades 545 to be forced inward to clamp and bind the binding strip held by the anvil positively about the box 115 form which has been made by the die mechanism and plunger mechanism in its upward movement, the reverse action of the lever 563 serving to move the clenching levers 546 away from the plunger head free of the anvil. Another important result secured by the sleeve 558 is that its lower end engages a shoulder on the tubular stem 466, thus pushing the anvil head 465 downward far enough to expose the anvil corner 125 pieces and to move the same into the plane of action through which the folding mechanism moves in putting the wire rim or binding metal on to the ram or plunger. This is done during the latter 130

part of the downward movement of the sleeve 558 or at the time the jaws 546 to 549 are almost opened.

The box is now completed but in case it should be held to the plunger when the die mechanism is lowered and to prevent the possibility of the box remaining on the plunger head, I provide a plurality of hooks or devices 569. These hooks are pivoted to opposite sides of two of the former plates of the die mechanism, that is former plates 480 and 482, and each hook has a part 570 which is adapted in the forward movement of the die to pass over the metal binding strip and on the downward movement of the die to strip the completed box from the plunger mechanism. Each of the hooks 569 is pivoted on a screw 571 and on the former plates is a stud 572. A second stud 573 is carried by the hooks 569 and connecting the two studs is a spring 573^a which tends to throw the hook against a stop 573^b, the construction being such that the hooks may readily pass upward past the binding strip and over the same at a point above the anvil so as to remove the same not only from the anvil but also the retaining hook or projection carried thereby, which latter holds the binding strip to the anvil while the box is being formed and the strip applied thereto.

The box after being stripped from the plunger lowers with the lowering of the die mechanism and while being lowered the die mechanism passes through the shoo receiver of the carrier and from which the crossed shooks were removed and formed into box shape and corners of the box enter V-shaped parts 574 projecting inward from the receiver frame. These V-shaped parts 574 are formed as a part of a bracket 575 and said bracket is fastened by screws 576 to projecting parts of the receiver frame. There are four brackets for each receiver frame equally spaced apart and said brackets are positioned in alinement with the corners of the box. The V-shaped portion 574 is slightly tapered according to the inclination of the sides of the box, being somewhat smaller at the bottom than at the top, and as the box engages the parts 574 of the brackets 575 it will remain seated in said brackets as shown at 577 in Fig. 104. The turret or carrier is then given a movement to place new shooks in a crosswise position under the die mechanism, as previously described and also to carry the completed box under the mouth of a chute 578. This chute 578 is supported in the machine frame and is substantially rectangular in cross-section and has a spring portion or top 579 at one end thereof. An ejecting device 580 is adapted to move under the chute 578 and this ejecting device has a part 581 which is held to the outer end of an arm 582. This

part 581 is adapted to fit the bottom of the box and the other end of the arm is secured to a shaft 583 which serves as a pivot for the arm 582, the latter being curved so that when said arm is moved, it will carry the box and force the same through the chute 578 to arrange the box over those previously completed in order to stack the same and to discharge the boxes so stacked from the machine. A reciprocatory rack 584 is in mesh with a gear 585 on the shaft 583, and which is held to move with the arm 582, and said rack, Figs. 104 and 105, is held to a rod 585, the lower end of which is pivotally connected to the arm 239^a. This arm 239^a is held to shaft 587 and on the outer end of said arm is a roll or trundle 588 which enters a groove in the cam 240. At each movement of the cam 240 the rod 585 will be operated which will reciprocate the rack 584 and through said rack rotate the arm 582 to cause the completed box 577 to be carried by the part 581 and stacked with the boxes already completed as already described.

The invention will be readily understood from the foregoing description when taken in connection with accompanying drawings. Assuming the parts to be in the position shown with a sufficient stock of tin or any other coated or incoated metal in the form of a long strip from a reel or otherwise, and the magazines supplied with veneer shooks 244^a, and the main shaft 45 rotated, the binding strip 10 will be fed inward and will be formed substantially V-shaped lengthwise thereof, and when thus formed will be tilted by the rolls 130 and 131, after which it is cut off the desired length. The metal binding strip is moved forward to meet the forming anvil and the said strip is bent on all sides thereof by the bending jaws 174 and 210, and the said binding strip formed so that its ends will overlap as previously described, the single strip being first bent around two corners of the anvil and then around the remaining two corners. The binding strip now being held by the anvil, the shooks previously picked up from one of the magazines 242 by one of the arms of the pneumatic suction device 365, the said shooks in pairs will be carried by the same arm crosswise of each other. The shooks arranged crosswise are discharged into one of the receiving frames of the turret or carrier 432 and are supported upon the elements 435 to 438 of the carrier. These elements are then moved slightly to aline the shooks and the carrier is then rotated to place the shooks over the die mechanism 464 and under the plunger mechanism 463 as already described. The presser foot 472 of the plunger mechanism is forced downward to engage the shooks in the carrier, and the die mechanism is then moved up-

ward and during the upward movement of the dies the ends of the shooks are bent into box form. The presser foot 472 moves upward with the die mechanism and the plunger is caused to enter the box and on further movement of the die mechanism the upper edge of the box is forced into the binding strip. The clencher levers 546 to 549 with blades 545 carried thereby are then forced inward by the mechanism previously described, which will cause the binding strip to be bound rigidly to the box form. During the upward movement of the die mechanism, the hooks 569 carried thereby will engage the upper edge of the binding strip and will force or strip the completed box from the plunger when the die mechanism is lowered. The completed box as the die mechanism is lowered is caught by the V-shaped ends 574 of the brackets 575 of the carrier, or the strip should there be no box, and after the mechanism is passed below the carrier, the latter is given a partial rotation to place the completed box under the chute 578. At this time the arm 582 is operated through the rack 584 by engagement with a gear 585 which will force the completed box from the carrier into the chute and until the box fits over the body of the box previously formed, each succeeding box being properly stacked so that a number of boxes may be removed at the same time, the spring parts 579 serving to engage the edges of the binding strip on all sides of the box 35 to hold the same against backward movement and in position while the boxes are being discharged.

The several mechanisms connected with the main drive shaft 45 have been described 40 the said shaft 45 being operated in any suitable way. As shown there is a pulley 590 which carries a gear 591 and this gear is in mesh with a larger gear 592, on the sleeve of which is a smaller gear 593, the latter gear meshing with the gear 594 on the shaft 45, though instead of the means described, any other means may be employed for rotating the said shaft 45 or for controlling the rotation of the same.

50 It will be understood that many changes may be made in the construction of the invention without departing from the character or nature of the same. As for example, the picker or pickers for removing the shooks and depositing the same in the box-forming mechanism may reciprocate along a track instead of rotate, and such a construction might be particularly adapted for machines for making the large size package. Instead of feeding the strips in the manner shown, two pulleys about the same size suitably connected to operate may be utilized to pay-out the binding strip from the spool or reel; and instead of equalizing 65 devices such as shown, rolls might be used

to guide the strip at the point where it is formed substantially V-shaped lengthwise thereof, or the said devices may be entirely dispensed with.

It will be also understood that any mechanism may be employed for stopping the feed by pressure acting upon the upper shook of the magazine or magazines. Electric as well as mechanical means may be employed for this purpose and instead of the feed screws being operated in the magazines as shown and described, they may be operated continuously through worms and gears with a steady rotary motion, or intermittent if preferred, and then have the feed stopped by a clutch which will disengage the drive from the worm. Instead of suction means, arms with penetrating points carried thereby may be used, and where pneumatic means is employed, the device may be flat instead of cup-shaped as shown. It will be further understood that instead of the rotary feed, where a large machine is used for the large sized packages, reciprocatory gripping devices may be employed.

Where the word "veneer" is used it is employed in its broadest sense and is intended to include any kind of material that may be utilized for making the box body 95 whether such material is paper, sheet pulp or of any other character.

From the foregoing, it will be seen that a machine for making boxes entirely automatic in its action is provided; that effective 100 means is provided for feeding a single strip and forming it into shape to be applied to the box; that simple means is provided for feeding the strip and for cutting the same transversely; that simple means is provided 105 for holding the strip and for bending it to conform to the shape of the box; that simple and effective automatic means is provided for feeding the shooks and for holding the same while being fed; that simple and efficient means is provided for picking shooks from the magazine and for conveying the same to the die mechanism and which is so timed with relation to the other parts of the machine that the said shooks will be carried and placed in position to be made into box form; that simple and efficient means is provided for forming the box and for applying the binding metal thereto; and that simple means is provided whereby the box when 110 completed may be automatically discharged from the machine and a number of boxes properly and automatically stacked.

Having thus described my invention, I claim as new and desire to secure by Letters Patent:—

1. In a box-making machine, the combination with means for bending a strip of binding metal, of means for forming box material into box form and for applying 130

the metal binding strip thereto, two magazines arranged at an angle with respect to each other, rotary and reciprocatory means for taking a single piece of box material in succession from each magazine and holding them cross-wise of each other, and independent rotary means for feeding the box material thus held to the box forming means.

2. In a box-making machine, the combination with means for bending a strip of binding metal, of means for forming box material into box form and for applying the metal binding strip thereto, shook-holding means, rotary and reciprocatory means for taking a single shook in succession from said holding means cross-wise of each other, and independent rotary means for feeding the shooks to the box forming means.

3. In a box-making machine, the combination with means for bending a strip of binding metal, of means for forming shooks into box form and for applying the metal binding strip thereto, means for holding the shooks, means for taking single shooks in succession from the holding means and an independent carrier for receiving the shooks and conveying the same to the box forming means.

4. In a box-making machine, the combination with means for forming a box from veneer shooks, of independent means for holding and feeding the shooks, a rotary and reciprocatory device independent of the holding and feeding means for removing the shooks in succession from the independent shook holding means, and means independent of the rotary and reciprocatory device and box-forming means for supporting and carrying the shooks to the box-forming means.

5. In a box-making machine, the combination with means for forming a box from blanks, of independent means for holding and feeding the blanks, a rotary and reciprocatory device for removing the blanks in succession from the independent blank holding means, and a carrier entirely independent of the rotary and reciprocatory device and the box-forming means for supporting and carrying the blanks to the box-forming means.

6. In a box-making machine, the combination with means for forming a box from blanks, of means for holding and feeding the blanks, a movable device for removing the blanks from the blank holding means and holding them crosswise, and a carrier entirely independent of said movable device and the box-forming means for supporting and carrying the blanks to the box-forming means.

7. In a box-making machine, the combination with means for forming a box, of means for bending and forming a metal binding

strip in box shape and for applying the same to the box when made, independent shook holding means, feeding means for the shooks, a carrier, and an independent rotary and reciprocatory device for removing the shooks from the independent holding means in succession and placing them cross-wise of each other in said carrier.

8. In a box-making machine, the combination with means for forming a box, of means for bending and forming a metal binding strip in box shape and for applying the same to the box when made, independent shook holding means, feeding means for the shooks, a carrier located at one side of the holding means, and an independent rotary device for removing the shooks from the independent holding means in succession and placing them cross-wise of each other in said carrier.

9. In a box-making machine, the combination with means for forming a box, of an independent shook holding means, feeding means for the shooks, a carrier, and an independent rotary and reciprocatory device for removing the shooks from the independent holding means in succession and placing them cross-wise of each other in said carrier.

10. In a box-making machine, the combination with means for forming and completing a box from veneer blanks or shooks, of a plurality of magazines, means for independently feeding the shooks in said magazines, and rotary pneumatic means having independent suction devices for the different shooks for removing the shooks in succession from the magazines and placing the same cross-wise.

11. In a box-making machine, the combination with means for forming and completing a box from the blanks, of a plurality of magazines, means for independently feeding the blanks in said magazines, and pneumatic means having independent suction devices at right angles to each other for removing the shooks in succession from the magazines and placing the same cross-wise.

12. In a box-making machine, the combination with means for forming and completing a box, of blank holding means, feeding means for the blanks, and rotary pneumatic means for removing the blanks independently and in succession and transferring the blanks and discharging them simultaneously.

13. In a box-making machine, the combination with box-forming means, of a carrier, independent shook holding means, a rotary device independent of the carrier having a plurality of suction heads, means for creating suction in said device, means for removing the shooks in succession from the independent shook holding means and

for placing them cross-wise in pairs, and means whereby the shooks may be simultaneously discharged into the carrier.

14. In a box-making machine, the combination with box forming means, of a carrier, shook holding magazines, feeding means for the shooks, together with a rotary and reciprocatory device independent of the carrier having a plurality of radially arranged arms, each provided with a head, and means whereby the heads may be made to remove the shooks in succession and place them cross-wise in the carrier.

15. In a box-making machine, the combination with box-forming means, of a carrier, shook holding means, together with a device independent of the carrier having a plurality of radially arranged arms, each provided with a suction head, and means whereby the heads may be made to remove the shooks and place them in the carrier.

16. In a box-making machine, the combination with box-forming means, of a plurality of independent shook-holding means and a rotary shook transfer device, comprising a plurality of radially-extending tubular arms, a head carried by each arm, two sets of suction devices carried by each head and arranged transversely of each other and adapted to hold the shooks cross-wise and in pairs, means for creating suction in the arms, and valves arranged in the arms and automatically actuated whereby suction may be created to hold the shooks to the heads or the suction cut off to permit the shooks to be discharged therefrom.

17. In a box-making machine, the combination with box-forming means, of a transfer device for box blanks, comprising a plurality of radially-extending tubular arms, a head carried by each arm, two sets of suction devices carried by each head and arranged transversely of each other and adapted to hold the blanks cross-wise and in pairs, and means for creating suction in the arms.

18. In a box-making machine, the combination with box-forming means, of a carrier, shook holding means, and a movable transfer device, comprising a plurality of tubular arms, a head carried by each arm, two sets of suction devices carried by each head and arranged transversely of each other and adapted to hold the shooks cross-wise and in pairs, means for creating suction in the arms and valves arranged in the arms and automatically actuated whereby suction may be created to hold the shooks to the heads or the suction cut off to permit the shooks to be discharged therefrom into said carrier.

19. In a box-making machine, the combination with means for forming a box, of shook holding means, and a rotary device having a head provided with two sets of suction devices arranged in close relation and

at an angle with respect to each other, and means whereby the head may be made to remove the shooks from the holding means one at a time and to hold them crosswise of each other.

20. In a box-making machine, the combination with means for forming a box, of shook holding means and an intermittently rotary and reciprocatory device having a plurality of heads each provided with two sets of suction devices arranged at an angle with respect to each other, and means whereby the head may be made to remove the shooks from the holding means.

21. In a box-making machine, the combination with means for forming a box, of means for making and applying a metallic binding to the box when made, independent shook holding means, a tubular shaft, means for raising and lowering said shaft, a plurality of radial tubular arms connected to said shaft, a head provided with two sets of suction devices, each adapted to hold a shook and having independent passages for the suction devices of each arm, independently movable valves for controlling the passages between the suction devices and said arms, means for creating suction in the arms, means for operating the valves independently, and means for imparting a rotary movement to the arms.

22. In a box-making machine, the combination with means for forming a box, of shook holding means, a shaft, means for raising and lowering said shaft, a plurality of tubular arms connected to said shaft, a head provided with two sets of suction devices, adapted to hold shooks cross-wise and having an independent passage for the suction devices of each arm, valves for controlling the passages between the suction devices and said arms, means for creating suction in the arms, means for operating the valves, and means for imparting a rotary movement to the shaft and arms.

23. In a box-making machine, the combination with means for forming a box, of independent shook holding means, a tubular shaft, means for raising and lowering said shaft, a head provided with two sets of cup-shaped suction devices and independent passages for the suction devices within each arm, valves for controlling the passages between the suction devices and said arms, and means for creating suction in the arms.

24. In a box-making machine, the combination of means for forming a box, independent holding and feeding means for box shooks, and a rotary device for independently removing the shooks in succession and having a head provided with two independent sets of suction devices, and means for controlling the suction of said devices.

25. In a box-making machine, the combi-

5 nation of means for forming a box, independent holding and feeding means for veneer shooks and a device for independently removing the shooks in succession and having a head provided with two independent sets of suction devices, and means for controlling the suction of said devices.

10 26. In a box-making machine, the combination with means for forming a box, of a carrier, a plurality of magazines, means for feeding the shooks upward in said magazines, a device having a plurality of heads, each provided with two sets of suction devices arranged transversely of each other, 15 each suction device being cup-shaped and having an independent communication with said head, said head having independent passages for the sets of suction devices, tubular arms carrying said heads, two movable valves, each operated in succession and each controlling one of the passages from one of the sets of the suction devices, springs normally forcing the valves in one direction, a rod for forcing the valves to an open position independently and in succession, arms for operating the rods, means for imparting a rotary movement to the arms and heads, and means for reciprocating the device to force the heads in succession into the magazine.

20 27. In a box-making machine, the combination with means for forming a box, of a magazine, means for feeding blanks or shooks upward in said magazine, a device having a plurality of heads, each provided with two sets of suction devices arranged transversely of each other, each suction device being cup-shaped and having an independent communication with said head, said head having independent passages for each 25 set of suction devices, tubular arms carrying said heads, and means for controlling the suction in said devices.

25 28. In a box-making machine, the combination with means for forming a box, of a carrier, a plurality of magazines, means for feeding the shooks upward in said magazines, a device having a plurality of heads, each provided with two sets of suction devices arranged transversely of each other, each suction device being cup-shaped and having an independent communication with said head, said head having independent 30 passages for the sets of suction devices, tubular arms carrying said heads, two valves, one operated through the other and each controlling one of the passages from one of the sets of the suction devices, a spring normally forcing the valves in one direction, and means for forcing the valves in the other direction.

35 29. In a box-making machine, the combination with means for forming a box, of a carrier, a plurality of magazines, means for feeding the shooks upward in said maga-

70 zines, a device having a plurality of heads, each provided with two sets of suction devices arranged transversely of each other, said head having independent passages for the sets of suction devices, tubular arms carrying said heads, two valves, each controlling one of the passages from one of the sets of the suction devices, springs normally forcing the valves in one direction, a rod for forcing the valves of each arm to an open 75 position, arms for operating the rods, and means for imparting a rotary movement to the arms and heads.

80 30. In a box-making machine, the combination with means for forming a box, of a plurality of magazines, means for feeding the shooks upward in said magazines, a device having a plurality of heads, each provided with two sets of suction devices arranged transversely of each other, tubular arms carrying said heads, two independently movable valves, one operated through the other and each controlling one of the 85 passages from one of the sets of the suction devices, springs normally forcing the valves in one direction, a rod for forcing the valves of each arm to an open position, means for operating the rods, means for imparting a rotary movement to the arms and heads, and means for reciprocating the device to 90 force the heads in succession into the magazines.

95 31. In a box-making machine, the combination with means for forming a box from veneer shooks, of means for forming and applying binding material to the box when made, a plurality of independent shook holding means, feeding means for the shooks, a rotary device for removing the shooks in succession from the independent holding means, rotary transfer means independent of said rotary device, together with means for reciprocating the rotary device and simultaneously acting to control the feed of the shooks.

100 32. In a box-making machine, the combination with means for forming a box, of a plurality of independent holding means for the blanks, feeding means for the blanks, a device independent of the holding and feeding means for removing the blanks in succession from the independent holding means, rotary means for supporting and carrying the blanks entirely independent of said device and the means for forming the 105 box, together with means for moving the device and simultaneously acting to control the feed of the blanks.

110 33. In a box-making machine, the combination with means for forming a box from veneer shooks, of shook holding means, feeding means for the shooks, a device for removing the shooks in succession from the holding means, rotary transfer means entirely independent of said device, together 115 120 125 130

with means for reciprocating the device and simultaneously acting to control the feed of the shooks.

34. In a box-making machine, the combination with means for forming a box, of two magazines, means for feeding shooks upward in said magazines, a rotary device having suction heads, means for creating suction in said heads, a drive shaft, means for rotating the device and said shaft, and a rock shaft connected to the rotary means of the device whereby the latter may be given an up and down movement to cause the heads to successively enter the magazines and remove the shooks therefrom. 70

35. In a box-making machine, the combination with means for forming a box, of a magazine, means for feeding shooks upward in said magazine, a rotary device having suction heads each having independent suction parts, means for creating suction in said heads, and means whereby the device may be given an up and down movement to cause the heads to enter the magazine and remove the shooks therefrom. 80

36. In a box-making machine, the combination with means for forming a box, of two magazines, means for feeding shooks upward in said magazines, a rotary device having suction heads each having independent suction parts, and means whereby the device may be given an up and down movement to cause the heads to successively enter the magazines and remove the shooks therefrom. 95

37. In a box-making machine, the combination with box-forming means, of means for holding shooks, a vertically reciprocating and horizontally rotary transfer device, together with a rotary carrier adapted to receive the shooks from said device and carry the same to the box-forming means. 105

38. In a box-making machine, the combination with box-forming means, of means for holding blanks, a rotary transfer device, together with a rotary carrier independent of the transfer device adapted to receive the blanks cross-wise from said device and carry the same to the box-forming means. 110

39. In a box-making machine, the combination with box-forming means, of means for holding blanks, a rotary transfer device independent of the blank holding means and the box-forming means, together with a carrier independent of said transfer device and the box-forming means adapted to receive the blanks cross-wise from said device and carry the same to the box-forming means. 115

40. In a box-making machine, the combination with box-forming means, of box shook holding means, means for removing the shooks and holding the same cross-wise, 125

a carrier having a plurality of independent receiving means for the shooks into which the latter are deposited cross-wise, and means for imparting an intermittent movement to the carrier to convey the shooks to the box-forming means. 130

41. In a box-making machine, the combination with box-forming means, of holding means for box blanks, means for removing the blanks and holding the same cross-wise, 75 a carrier having a plurality of independent receiving means each having movable elements for the blanks into which the latter are deposited cross-wise, and means for imparting an intermittent rotary movement to the carrier to convey the blanks to the box-forming means. 80

42. In a box-making machine, the combination with box-forming means comprising vertically movable plunger and die elements, 85 of a carrier adapted to hold shooks and to convey the same between the plunger and die elements of the box-forming means, means for operating the die and the plunger elements to remove the shooks from the carrier and to form the same box-shape by the movement of the die and plunger elements, and means whereby the completed box may be discharged and held in the carrier and conveyed by the latter away from the die 95 elements at the same time placing new shooks between the die and plunger elements to be formed into box shape. 90

43. In a box-making machine, the combination with a box-forming means comprising bodily movable plunger and die elements, of a carrier adapted to hold shooks and convey the same between the plunger and die elements, and means for operating the die and the plunger elements toward each other and 100 then together to remove the shooks from the carrier and to form the same box-shape. 105

44. In a box-making machine, the combination with box-forming means comprising bodily movable plunger and die elements, of a carrier adapted to hold shooks and convey the same between the plunger and die elements, means for operating the die and the plunger elements to remove the shooks from the carrier and to form the same box-shape 110 115 by the movement of the die and plunger elements, and means whereby the completed box may be discharged and held in the carrier. 120

45. In a box-making machine, the combination with box-forming means, of a carrier having a plurality of independent receivers for shooks and adapted to hold the same cross-wise, means for placing the shooks cross-wise in the receivers of the carrier, pivotally held elements adapted to support the shooks at their ends and located in each receiver, and means for automatically actuating the elements to align the shooks. 125

46. In a box-making machine, the combi- 130

5 nation with box-forming means, of a carrier having a plurality of independent receivers, opposed swinging elements arranged in pairs in each receiver adapted to support box blanks at their opposite ends only and means for moving the elements of each pair toward or away from each other.

10 47. In a box-making machine, the combination with box-forming means, of a carrier having a plurality of independent receivers for shooks and adapted to hold the same cross-wise, means for placing the shooks cross-wise in the receivers of the carrier, and pivotally held supporting elements adapted 15 to support the shooks at their ends and located in each receiver.

20 48. In a box-making machine, the combination with box-forming means, of a carrier having a plurality of receivers each receiver 25 having four pivotally held alining elements adapted to support shooks cross-wise, and means for automatically moving said elements to aline the shooks.

25 49. In a box-making machine, the combination with box-forming means, of a carrier having a receiver provided with four pivotally held alining elements adapted to support shooks cross-wise one over the other, and means movable above the carrier for depositing the shooks crosswise in said carrier so as to be held by the alining elements.

30 50. In a box-making machine, the combination with box-forming means, of shook-holding means, means for transferring the shooks, and a carrier for receiving the shooks from the transfer means and for conveying the same to the box-forming means, said carrier comprising a plurality of receivers, two pivotally held elements for each 35 shook arranged in each receiver adapted to support the shooks crosswise of each other and at their ends, rods connecting the elements in pairs, springs tending normally to force the elements in one direction, and independently movable cams adapted to move the rods and swing the elements of each receiver independent of the rotary movement of the carrier to aline the shooks, and means for rotating the carrier to place the shooks adjacent to the box-forming means.

40 51. In a box-making machine, the combination with box-forming means, of a carrier for shooks, said carrier having a receiver, a plurality of pivotally held elements adapted 45 to support box shooks cross-wise of each other and at their ends, rods connecting the elements in pairs, and means for operating the rods to aline the shooks.

45 52. In a box-making machine, the combination with box-forming means, of shook-holding means, means for transferring the shooks, and a carrier for receiving the shooks from the transfer means and for conveying the same to the box-forming means,

5 said carrier comprising a plurality of receivers, a plurality of pivotally held elements for each shook arranged in each receiver adapted to support the shooks cross-wise of each other, rods connecting the elements in pairs, springs tending normally to 10 force the elements in one direction, and means adapted to move the rods and swing the elements of each receiver independent of the movement of the carrier to aline the shooks.

75 53. In a box-making machine, the combination with box-forming means, of shook-holding means, and a carrier for the shooks for conveying the same to the box-forming means, said carrier comprising a plurality of receivers, movable elements arranged in each receiver adapted to support the shooks, rods connecting the elements in pairs, springs tending normally to force the elements in one direction, independently movable means adapted to move the rods and the elements of each receiver independent of the rotary movement of the carrier to aline the shooks, and means for rotating the carrier to place the shooks adjacent to the box-forming means.

80 54. In a box-making machine, the combination with bodily movable box-forming means, of a carrier having a plurality of receivers each adapted to hold two shooks cross-wise of each other, means for rotating said carrier, devices carried by each receiver adapted to receive and support the box after the same has been completed by the box-forming means, together with means for forcing the completed box into the receiver of the carrier.

85 55. In a box-making machine, the combination with bodily movable box-forming means, of a carrier having receivers adapted 95 to hold two shooks cross-wise of each other, means for rotating said carrier, devices adapted to receive and support the box after the same has been completed by the box-forming means, together with means for forcing the completed box into the receiver of the carrier.

90 56. In a box-making machine, the combination with bodily movable box-forming means, a carrier, means for rotating said carrier, and devices mounted on the carrier adapted to receive and support the box after the same has been completed by the box-forming means.

100 57. In a box-making machine, the combination with means for supplying shooks cross-wise, of box-forming means comprising die elements lying normally below the shook-supplying means, a plunger element located normally above the shook-supplying means, means for forcing the die and plunger elements toward each other to remove the shooks from the supplying means and to

- form the same box shaped, and means whereby the completed box may be removed from the box forming means. 58. In a box-making machine, the combination with means for supplying shooks cross-wise, of box-forming means comprising die elements lying normally below the shook-supplying means, a plunger element located normally above the shook-supplying means, and means for forcing the die and plunger elements toward each other to remove the shooks from the supplying means and to form the same box shaped. 59. In a box-making machine, the combination with a movable carrier adapted to hold shooks cross-wise, of box-forming means comprising die elements lying normally below the carrier, a plunger element located normally above the carrier and means for forcing the die and plunger elements toward each other to remove the shooks from the carrier and to form the same box shaped. 60. In a box-making machine, the combination of a vertically movable plunger, of an independently movable presser foot, a movable die element, and means for placing box blanks cross-wise between the die element and the presser foot element. 61. In a box-making machine, the combination with a movable plunger, an independently movable presser foot forming a part of the plunger, a movable die element, and means for placing shooks cross-wise between the die element and the presser foot element. 62. In a box-making machine, the combination with a movable plunger having a presser foot, of a movable die element, and means for placing shooks cross-wise between the die and the presser foot element. 63. In a box-making machine, the combination with a vertically reciprocatory plunger conforming substantially to the shape of the box to be formed, an independently movable presser foot forming a part of the plunger, means for placing shooks cross-wise under the presser foot, and die mechanism comprising a base and forming sides normally located beneath the shook-supplying means and coöperating with the plunger to form the box into box shape, means for binding the shooks together to complete the box, and means for removing the completed box from the box forming means and for conveying the same therefrom. 64. In a box-making machine, the combination with a movable plunger conforming substantially to the shape of the box to be formed, means for placing shooks cross-wise under the plunger, and movable die mechanism comprising a base and forming sides normally located beneath the shook-supplying means and coöperating with the plunger to form the box into box shape. 65. In a box-making machine, the combination with a movable plunger conforming substantially to the shape of the box to be formed, bodily movable die mechanism comprising a base and forming sides located beneath the plunger and coöperating with said plunger to form the box into box shape, and means for removing the completed box from the box forming means and for conveying the same therefrom. 66. In a box-making machine, the combination of shook-holding means, a plunger having pivotally held members forming the sides of the plunger, a presser foot forming a part of the plunger adapted to engage and rest on said shooks, a die located beneath the plunger and presser foot, members pivotally held to the die and adapted to be moved upward on their pivots to fit about the members of the plunger and to fold the shooks about the plunger and presser foot, and means for imparting a relative movement to the plunger and die. 67. In a box-making machine, the combination of shook-holding means, a plunger having pivotally held members forming the sides of the plunger, a die located beneath the plunger, folding members held to the die and adapted to be moved to fit about the members of the plunger and to fold the shooks during such movement, and means for moving the plunger and die toward each other. 68. In a box-making machine, the combination with means for holding shooks cross-wise, of a movable plunger normally located above the shook-holding means, a movable die normally located under the shook-holding means, and means for bodily moving the die to remove the shooks from the holding means and to coöperate with the plunger to form the shooks into box shape. 69. In a box-making machine, the combination with rotary means for holding box blanks, of a movable plunger normally located on one side of the blank-holding means, a movable die normally located on the other side of the blank-holding means, and means for causing the die to bodily remove the blanks away from and carry them beyond the holding means and to coöperate with the plunger during such movement to form the blanks into box shape. 70. In a box-making machine, the combination with a carrier, adapted to hold box blanks, of bodily movable box-forming means having means which move in opposite directions and then together in the same direction and which removes the blanks from the carrier and forms the blanks into box shape independent of said carrier. 71. In a box-making machine, the combination of means for holding shooks cross-wise, bodily movable plunger mechanism, means for supporting binding material

about the plunger, clenching mechanism, bodily movable die mechanism located normally on the side of the shook-holding means opposite to that of the plunger and having movable members adapted to form the shooks into box form, and means for moving said members of the die mechanism.

72. In a box-making machine, the combination of means for holding the box blanks cross-wise, movable plunger mechanism, movable die mechanism located normally below the shock-holding means and having movable members adapted to coöperate with the plunger mechanism and remove the 15 blanks from the holding means and to form said blanks into box form, means for moving the members of the die mechanism, and means for forcing the box when made into the blank-holding means.

73. In a box-making machine, the combination with shook-holding means adapted to hold the same cross-wise, of die mechanism comprising a base having yielding portions, members for forming the sides of the box 25 pivotally held at one end to the base, a die head having cam portions, levers connected to the pivotal die members and engaging the cam portions of the die head, a sleeve connected to move all of the die members in 30 unison, means for imparting a movement to the die as a whole, and plunger mechanism including relatively movable members adapted to coöperate with the die to form the shooks into box-form.

74. In a box-making machine, the combination with shook-holding means adapted to hold the same cross-wise, of die mechanism comprising a base having yielding portions, members for forming the sides of the box 40 pivotally held at one end to the base, and plunger mechanism including relatively movable members adapted to coöperate with the die to form the shooks into box-form.

75. In a box-making machine, the combination with shook-holding means, of die mechanism comprising a base, members for forming the sides of the box pivotally held at one end to the base, a die head having cam portions, levers connected to the pivotal 50 die members and engaging the cam portions of the die head, means for imparting a movement to the die as a whole, and plunger mechanism adapted to coöperate with the die to form the shooks into box-form.

76. In a box-making machine, the combination with shook-holding means, of means for supplying the shooks cross-wise to said holding means, die mechanism comprising a base, movable members for forming the 60 sides of the box, a die head having cam portions, levers connected to the movable die members and engaging the cam portions of the die head, means for moving all of the die members in unison, means for imparting a movement to the die as a whole, and plunger

mechanism coöperating with the die to form the shooks into box-form.

77. In a box-making machine, the combination with shook-holding means adapted to hold the same crosswise, of die mechanism 70 including movable members adapted to form the sides of the box, a plunger having a presser foot serving as a form for the bottom of the box and having pivotal sides adapted to fit within the movable sides of 75 the die, means for supporting a binding strip on the plunger, means for imparting relative movements to the die and plunger to form the box and to apply the strip to the same when formed, and clenching mechanism for 80 binding the strip to the box.

78. In a box-making machine, the combination with movable shook-holding means, of movable die mechanism located under the shook-holding means including movable members adapted to form the sides of the box, a movable plunger located above said shook-holding means and having a presser foot serving as a form for the bottom of the box and having pivotal sides adapted to fit within the movable sides of the die, and means for imparting relative movements to the die and plunger to carry the shooks away from the holding means and during such movement form the box.

79. In a box-making machine, the combination with shook-holding means adapted to hold the same cross-wise, of die mechanism including movable members adapted to form the sides of the box, a plunger having a relatively movable presser foot serving as a form for the bottom of the box and adapted to fit within the movable sides of the die, means for supporting a binding strip on the plunger, and means for imparting relative movements to the die and plunger to form the box and to apply the strip to the same when formed.

80. In a box-making machine, the combination with shook-holding means, of die mechanism including movable members adapted to form the sides of the box, a plunger having a relatively movable presser foot serving as a form for the bottom of the box and having pivotal sides adapted to fit within the movable sides of the die, means for bending a binding strip box shape, means for supporting the binding strip on the plunger, means for imparting relative movements to the die and plunger to form the box and to apply the strip to the same when formed, and clenching mechanism for binding the strip to the box.

81. In a box-making machine, the combination with shook-holding means adapted to hold the same cross-wise, of die mechanism, a plunger mechanism coöperating therewith to form the shooks in box form, means for forming and holding a binding strip about the plunger, a plurality of levers having a

5 clencher plate attached thereto, one for each side of the box, means for rocking the levers to force the binding strip into locking engagement with the shooks, and levers having hook-shaped ends carried by the die mechanism and adapted to engage the upper edge of the box when completed and to strip the same from the plunger, and means whereby the completed box may be discharged in and 10 held by the shook-holding means.

15 82. In a box-making machine, the combination with shook-holding means, of movable die mechanism independent of the shook-holding means, a bodily movable plunger mechanism coöperating therewith to form the shooks in box form, means for forming and holding a binding strip, and means whereby the binding strip may be applied to the box form.

20 83. In a box-making machine, the combination with shook-holding means adapted to hold the same cross-wise, of bodily movable die mechanism, a movable plunger mechanism located normally above the die 25 mechanism and coöperating therewith to form the shooks in box form, means for forming and holding a binding strip about the plunger, a plurality of levers having a clencher plate attached thereto, one for 30 each side of the box, and means for rocking the levers to force the binding strip into locing engagement with the shooks.

35 84. In a box-making machine, the combination with a carrier adapted to hold shooks cross-wise, of bodily movable die mechanism normally located beneath the carrier, bodily movable plunger mechanism located above the carrier, means for imparting a relative movement to the plunger mechanism and 40 die mechanism to remove the shooks from the carrier and to form the same box shape, devices held to the carrier and having V-shaped portions located in position to correspond with the corner of the box when 45 formed, means for forcing the completed box into said devices, and means whereby the completed box may be removed from the die and plunger mechanism.

50 85. In a box-making machine, the combination with a carrier adapted to hold box shooks, of bodily movable die mechanism normally located on one side of the carrier, bodily movable plunger mechanism located on the other side of the carrier, means for imparting a relative movement to the plunger mechanism and the die mechanism to remove the shooks from the carrier and to form the same box shape, brackets held to the carrier and having portions located in 55 position to correspond with the corner of the box when formed, and means whereby the completed box may be deposited into said brackets.

60 86. In a box-making machine, the combination of a carrier adapted to hold shooks,

bodily movable die mechanism normally located on one side of the carrier, bodily movable plunger mechanism located on the other side of the carrier, means for imparting a relative movement to the plunger 70 mechanism and the die mechanism to remove the shooks from the carrier and to form the same box shape, and brackets held to the carrier and adapted to receive and hold the completed box. 75

80 87. The combination with box-forming means, of a carrier, means for rotating the carrier, means for discharging box shooks cross-wise into the carrier, means for supporting a box in the carrier, means for discharging the box when completed into the carrier, a chute, and means whereby the completed box may be forced upward from the carrier into the chute and to fit over the box previously made. 85

88. The combination with box-forming means, of a carrier, means for rotating the carrier, means for supporting a box in the carrier, means for discharging the box when completed into the carrier, a chute 90 located above the carrier, and means whereby the completed box may be forced into and through the chute.

95 89. In a box-making machine, the combination with a carrier, having means to support a box, of a chute located above the carrier and having a curved body portion, one part of which is yielding and adapted to engage under a part of the box, a device having an arm adapted to remove the box from the carrier and force the same upward through the chute so as to fit over the box previously made, a pinion movable with the arm, a rack engaging the pinion and means for reciprocating the rack. 100

105 90. In a box-making machine, the combination with a carrier having means to support a box, of a chute located above the carrier and having a curved body portion, and provided with yielding means adapted to engage under a part of the box, a device having an arm adapted to remove the box from the carrier and force the same upward through the chute so as to fit over the box previously made, a pinion movable with the arm, a 110 rack engaging the pinion, and means for reciprocating the rack.

115 91. In a box-making machine, the combination with a carrier having brackets to support a box, of a chute located adjacent to the carrier and above the same, a device having an arm adapted to remove the box from the carrier and force the same upward into the chute, a pinion movable with the arm, a rack engaging the pinion, and means for reciprocating the rack. 120

125 92. In a box-making machine, the combination with a carrier, having means to support a box, of a chute located above the carrier and having a curved body portion, a 130

device having an arm adapted to remove the box from the carrier and force the same upward through the chute so as to fit over the box previously made, a pinion movable 5 with the arm, and means engaging the pinion to move the arm and device.

93. In a box-making machine, the combination with box-forming means, of a carrier for moving the box blanks adjacent to 10 said box-forming means, supporting brackets held to the carrier adapted to receive a box and support the same, means for rotating the carrier, a chute having a spring portion at one end, a device adapted to engage a box supported by the carrier, an arm held to the device, a pinion held to move the arm, a rack engaging the pinion, and means for reciprocating the rack to oscillate the device and force the box from the carrier 20 through the chute and over the box previously made so as to automatically stack the boxes.

94. In a box-making machine, the combination with box-forming means, of a carrier 25 for moving the box blanks adjacent to said box forming means, supporting brackets held to the carrier adapted to receive a box and support the same, means for rotating the carrier, a chute located above the carrier and having a spring portion at one end, a device adapted to engage a box supported by the carrier, and means for oscillating said device.

95. In a box-making machine, the combination with means for bending a strip of 35 binding metal, of means for forming box material into box form and for applying the metal binding strip thereto, two shook-holding magazines arranged at an angle 40 with respect to each other, and movable means for taking a single shook in succession from each magazine and holding them crosswise of each other, the two magazines being so arranged that the movable means 45 in removing the shooks will of itself cause them to be arranged crosswise of each other.

96. In a box-making machine, the combination with means for bending a strip of 50 binding metal, of means for forming box material into box form and for applying

the metal binding strip thereto, shook-holding magazines arranged at an angle with respect to each other, rotary and reciprocating means for taking the shooks from 55 the magazines and holding them crosswise of each other, the magazines being so arranged that the rotary and reciprocating means in removing the shooks will of itself cause them to be arranged crosswise of each 60 other, and means for feeding the shooks thus held to the box-forming means.

97. In a box-making machine, the combination with means for bending a strip of 65 binding metal, of means for forming veneer shooks into box-form and for applying the metal binding strip thereto, shook-holding magazines, a plurality of means for taking the shooks from the magazines in succession and holding them crosswise of each 70 other, certain of said means acting at the same time to remove the shooks one at a time from the magazines and for holding the same cross-wise of each other and in pairs, one of said shook-removing means being made to discharge a pair of shooks at the same time that the shooks are removed from the magazines, and means for feeding the shooks to the box-forming means.

98. In a box-making machine, the combination with means for bending a strip of 75 binding metal, of means for forming veneer shooks into box form and for applying the metal binding strip thereto, two shook-holding magazines, three devices for taking 80 the shooks from the magazines in succession and holding them crosswise of each other, two of said devices acting at the same time to remove the shooks one at a time from the magazines and for holding the 85 same crosswise of each other and in pairs, one of said shook-removing devices being made to discharge a pair of shooks at the same time that the shooks are removed from the magazines, and means for feeding the 90 shooks to the box-forming means.

This specification signed and witnessed this 12th day of August, A. D. 1911.

CHARLES BURNHAM.

ANTON GLOETZNER, Jr.,
P. H. ENRIGHT.

Corrections in Letters Patent No. 1,119,340.

It is hereby certified that in Letters Patent No. 1,119,340, granted December 1, 1914, upon the application of Charles Burnham, of Los Angeles, California, for an improvement in "Box-Making Machines," errors appear in the printed specification requiring correction as follows: Page 10, line 29, for the reference-numeral "2" read *212*; same page, line 77, for the word "bole" read *bolt*; page 15, line 11, for the reference-numeral "377" read *371*; page 20, line 46, for the word "alinemnet" read *alinement*; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
